UNITED STATES PATENT OFFICE.

JOSEPH LOUIS KIEFFER, OF MONTREAL, CANADA.

SHOE AND LEATHER SEWING MACHINE.

SPECIFICATION forming part of Letters Patent No. 742,998, dated November 3, 1903.

Application filed May 1, 1902. Serial No. 106,493. (No model.)

To all whom it may concern:

Be it known that I, JOSEPH LOUIS KIEFFER, a subject of the King of Great Britain, residing at the city of Montreal, Province of Quebec, Canada, have invented certain new and useful Improvements in Shoe and Leather Sewing Machines, (Stitchers;) and I do hereby declare that the following is a full, clear, and exact description of the invention, such as will enable others skilled in the art to which it appertains to make and use the same.

My invention relates to improvements in shoe-sewing machinery of that class known technically as the "outsole-stitcher"—that is to say, to a machine adapted to sew the sole of the shoe to the welt thereof and to form a lock-stitch by means of two interlocking threads which are looped together in the well-known manner of sewing-machines.

It is the object of my present invention to improve the machine in question in various ways by providing improved and easier methods of handling and adjusting, new and improved modes of forming the stitch, of regulating the position of the lock, measuring the thread, drawing up the thread, feeding and positioning the work, and in general improving the operation and adjustment of the machine as a whole, so as to enable it to do more and better work, to be more easily adjusted and more exactly set than was formerly possible in those machines which have been hitherto made so far as known to me.

A special object of my invention is to provide an entirely new mode of forming the stitch, to dispense entirely with the thread-carrying shuttle, and to carry the bobbin of thread formerly carried by the shuttle in a stationary position in the machine while the machine-thread is caused to be looped around it. The advantage of this arrangement lies in avoiding the twist both in the bobbin-thread and in the lock, caused by the inter-looping threads, which twist is incident to the employment of a rotary shuttle and is caused to be taken in the machine or bobbin thread at the point where it links into the opposing thread, forming a kind of knot, and making it especially difficult to draw the lock through the hole in the leather and properly position it thereon. In cloth-sewing machines, in which this type of apparatus

was originally used, a twist in the thread adjacent to the lock was highly advantageous, because the sinuous and pliable nature of the cloth would not hold a plain loop against being pulled out by drawing upon one of the threads, and this feature has been engrafted into shoe-sewing machinery along with the apparatus which accomplishes it. In sewing leather, however, the operation is vastly different, because of the far greater thickness of the leather and also of its greater stiffness and unyielding nature, which not only makes such a twist in the thread entirely useless, but actually disadvantageous in the manner just pointed out, and, furthermore, it may be stated that it is necessary in stitching leather to position the lock of the thread very precisely between the two faces of the seam, and the twist caused by the looping process of the rotary shuttle prevents this being done. A subordinate object of my invention in this connection is to provide means for delivering the loop of machine-thread gradually from frictional contact with the point of the thread-hook in its rotating motion, thus preventing any sudden jerk of the loop over the point of the hook, which is apt to cut the thread.

Another object of my invention is to so improve the pull-off mechanism as to permit of the necessary amount of thread being drawn from the wax-pot for the leather which is being stitched at each reciprocation of the needle, while at the same time dispensing with a projecting part of the machine which is present for this purpose in the machine formerly used. In the latter machine the pull-off mechanism projected out at the rear, being carried by an arm at the opposite side of one of the cam-levers, and this projection was not only objectionable as being in the way and liable to become broken, but it was especially objectionable as being too close to the pivot of the lever on account of its necessary relation to the wax-pot, so that the motion of the pull-off fork was insufficient to enable enough thread to be drawn from the tension-wheel to supply a heavy seam, whereby the thread was caused to break upon coming to a thick piece of leather.

It is therefore my object to reorganize the parts, as above referred to, so as to give an ample degree of reciprocation to the pull-off

fork, while at the same time getting it out of the way and placing it in a more convenient position for coöperation with the measuring mechanism which is operated by the motion 5 of the table.

Another object of my invention is to improve and reorganize the structure of the thread-measuring device, this object being partially in connection with that heretofore 10 mentioned relative to the auxiliary take-up arm—that is to say, in my improved construction of parts the thread-measuring device is got out of the way of the descending cam-levers, whereby to permit the latter greater latitude 15 of motion and to remove the danger of any of the parts becoming broken and generally to improve the operation of the machine.

Another object of my invention is to provide 20 an improved and easier-operated device for regulating the position of the lock in the seam, which is a very important adjunctive function of leather-sewing machinery, and to provide means whereby the same may be precisely 25 regulated by a milled headed screw, this improvement being constructed to co-operate with my improvement in the pull-off mechanism above referred to.

Another object of my invention is to provide 30 an improved construction of the bobbin-case and bobbin carrying the bobbin-thread heretofore carried by the shuttle of the machine, but in my present construction mounted so as to be stationary, as hereinabove mentioned. My object, more particularly speaking 35 in this connection, is to provide means whereby the bobbin may be readily extracted from and inserted into the case, to prevent the bobbin from becoming loose upon its spindle, to provide for the frequent renewal of the wearing parts, and generally to improve the construction and manipulation of the same.

Another object of my invention is to improve the construction of the thread-finger, 45 which is provided in this type of machines to coöperate with the looper in drawing back the thread, so that the same may be wound about the needle. This thread-finger has a further function in my machine of drawing 50 the loop taut about the hook of the needle, and by a peculiar arrangement of the cam which operates the thread-finger it is caused to give a further advantageous movement to the latter, which is pivoted to move about an 55 axis somewhat differently positioned from that in the former type of machines.

To these ends my invention consists in various important features which effectuate the above objects, and these features may be 60 briefly outlined as follows before proceeding with the general description of the machine.

Perhaps the most important and novel feature displayed in my improved stitcher is that relating to the stitch mechanism, which, 65 as hereinbefore referred to, embodies a stationary bobbin-carrying thread and means for drawing the loop of the machine-thread

over the same. The bobbin itself is mounted to rotate upon a spindle carried in the center of a bobbin-case through a hole in which the 70 bobbin-thread passes, and this bobbin-case is loosely retained in the center of a box or casing of flat cylindrical form covered and completed by a bracket which permits a certain amount of play of the said bobbin-case in its 75 box and sufficient space all around the same to permit the thread-loop of the machine-thread to pass thereover. This bobbin-case is held stationary, not by any solid connection with the box in which it is placed, but 80 by a small depending lip, which points downwardly and while engaging in a shallow recess in the bracket forming the cover of the bobbin-box permits the loop of machine-thread to pass easily thereover. The means 85 for drawing the loop of machine-thread over the bobbin-case comprises a curved or arcuate hook having a forwardly-directed point adapted to enter the loop of thread brought up from the work by the needle and a recurved nose or bill adapted to seize the thread-loop and draw it backwardly. This 90 arcuate thread-hook is caused to oscillate backwardly and forwardly around the bobbin in its box and in a circular raceway 95 formed by the exterior portion of the bobbin-box and around the circumference of the latter. The thread-hook is further secured to a rock-arm extending from an oscillating spindle or rock-shaft to which motion is imparted by a suitably-designed cam revolving 100 on the main shaft of the machine. The above-mentioned thread-hook is also formed with a groove in its rear face which is adapted to embrace the end of the needle and deliver 105 the thread therefrom just before the said thread is caught by the recurved nose or bill of the hook and drawn backwardly by the latter in its receding motion over the bobbin, and it further has a grooved tail-shield, which 110 is adapted to cover the needle during the pulling down of the loop by the take-up motion after it has been drawn over the bobbin-case to prevent the said loop becoming entangled with the barb of the needle. It is 115 to be observed that this oscillating thread-hook and stationary bobbin take the place of the oscillating or continuously-rotating shuttle heretofore employed, which carried the bobbin with it and through each successive 120 loop of machine-thread.

Another feature of my invention used in connection with the above-mentioned thread-hook is the improved means employed by me for spreading or opening the loop on the receding motion of the thread-hook, the said means consisting of a finger which is adapted to be inserted into the loop and to have a slight oscillating motion given it through the medium of a cam on the main shaft properly 125 timed to catch and push back the side of the thread-loop carried by the thread-hook on its receding motion, and thereby to lift the lap of the thread-loop away from the point of the 130

hook, whereby the thread is prevented from snapping over and becoming cut or abraded by the latter.

In that feature of my improved machine which relates to the pull-off mechanism I dispense with the rearwardly-extending arm forming a part of the needle cam-lever in the formerly-used type of machine, which arm had secured thereto the pull-off fork at the end thereof, and instead thereof I provide upon the main portion of the awl-lever itself, just forwardly of the main shaft, a thread-measuring truck, which is pivoted to the cam-lever and has a much greater degree of motion than was possible in the old type of machine. This truck comprises a depending arm having a slot therethrough through which passes the thread, and coöperating with it are two small thread rolls or studs, one on each side thereof, which hold the thread down while the said thread-measuring truck draws a certain amount of thread upwardly upon the backward motion of the awl. The amount of thread drawn up upon the upward motion of the truck may be regulated by means of a screw-bolt having a grooved end which projects upwardly through the end of the truck to a variable distance and forms, essentially, the bottom of the slot through which the thread passes. Moreover, the two said thread rolls or studs which coöperate with the truck are not stationary, but they are each mounted to have a different adjustment and to be turned up or down in connection with other parts of the apparatus, which will be presently referred to.

The arrangement of the forward thread-roll of the pair just referred to is similar to that employed in the present form of stitcher, being connected by an intermediate link with a locking-block which is adapted to be reciprocated by the table, and is arranged to provide more or less thread, in accordance with the thickness of the seam; but my especial construction is in the form of a small arched piece, which is pivoted on one side in the frame of the machine and is so shaped as to get it out of the way of the descending cam-levers, and thus provide more space for the operation of the said levers.

The rearmost of the pair of thread rolls or studs above mentioned, which coöperate with the thread-measuring truck, is mounted to oscillate on a small pivoted plate, which is connected by a link with an adjusting-screw having a milled head operable from the rear of the machine whereby to move said roll up or down, and thus increase or decrease the length of the loop pulled off by the thread-measuring truck; and the especial object of this roller is not to increase the length of thread in proportion to the thickness of the seam, but to enable the exact positioning of the thread-lock in the seam at a fixed distance from the upper surface thereof, and this thread-roll therefore remains stationary during the operation of the machine upon

any given piece of work, but is adjustable for different pieces of work by hand. The arrangement of this device, as just referred to, forms another feature of my invention.

Still another feature of my invention consists in the improved arrangement of the bobbin within its case, above referred to in relation to the thread mechanism, although this feature of my invention is equally applicable to shuttle-machines and others in which a bobbin-thread separate from the machine-thread is employed. The bobbin herein is not directly mounted upon the central post in the case; but there is interposed a wear-sleeve, which is formed with a projecting key interlocking with a groove in the interior surface of the hub of the bobbin. The wear-sleeve is itself mounted to turn loosely upon the central post or spindle carried by the bobbin-case, but is prevented by a shoulder on the outer end of said post from coming off of the latter, against which shoulder it is pressed by a plate-spring abutting against its inner end and producing the necessary friction to prevent the momentum of the bobbin carrying it beyond that point which is necessary to secure just enough thread for the use of the seam. The said central post is not formed integral with the bobbin-case; but, on the contrary, has a screw-threaded stud on its inner end, which is adapted to be screwed into a socketed boss in the back of the case, whereby the wear-sleeve is placed upon the said post before it is screwed up into its position. The bobbin, on the contrary, while prevented by its keyed connection with the wear-sleeve from rotating therewith, may be readily slid off the wear-sleeve and over the end of the post, because the shoulder thereof is not large enough to interfere therewith, and to hold the bobbin in its position I provide a small clip on the outer end of the post, which hooks over the hub of the bobbin. In this manner it will be seen that while the bobbin may be readily slipped on and off without in any way interfering with the rest of the machine or even removing the bobbin-case from the machine, yet it is subjected to no wear while rotating on the spindle-post and at the same time the necessary friction to check its momentum is at all times present.

Another feature of my invention consists in the improved position and motion given to the thread-finger, whereby the latter is drawn across the thread in the process of looping and is subsequently given a pair of successive small jerks by means of a pair of successive small jogs formed upon the cam which operates the said thread-finger, these jerks being adapted to release the loop of thread by successive small amounts necessary to relieve the abrasion of the thread caused by pulling it through the barb of the needle.

My invention further consists in the particular construction and combination of parts hereinafter to be described and which will appear from the detailed description herein-

after given, and are more particularly pointed out in the claims accompanying this specification.

I have illustrated the most approved form 5 of my improved stitcher in the accompanying drawings, wherein—

Sheets 1 to 6, inclusive, show general views of the machine. Sheet 7 is a view mainly of the stationary or frame parts. Sheets 8 to 11, 10 inclusive, illustrate the stitching mechanism. Sheet 12 illustrates principally the gage-adjusting device; Sheet 13, the spreading-finger mechanism; Sheet 14, the feed arrangements, and Sheets 15 and 16 the parts relative to the 15 thread measuring and regulating mechanism. More specifically, Figure 1, Sheet 1, is a plan view of the complete machine. Fig. 2, Sheet 2, is a front elevation thereof. Fig. 3, Sheet 3, is a side elevation thereof from the left- 20 hand side of the machine with the balance-wheel removed. Fig. 4, Sheet 4, is a side elevation from the right of the machine. Fig. 5, Sheet 5, is a vertical section from front to rear, taken approximately on the line 25 5 5 of Fig. 1 looking toward the right. Fig. 6, Sheet 6, is a similar section approximately on the line 6 6 of Fig. 1 looking toward the left. Fig. 7, Sheet 7, is a side elevation of the casting constituting the main portion of the frame 30 and the base thereof. Fig. 8, Sheet 7, is a perspective view of the complete frame, showing the operating parts removed and the several posts adapted to support the shafts and levers clamped in position thereto. Fig. 9, 35 Sheet 7, is a front elevation of the same piece as that shown in Fig. 7. Fig. 10, Sheet 8, is a perspective view from the rear, showing the operative parts of the stitching mechanism *in situ*. Fig. 11, Sheet 8, is a perspective 40 view of the gear-segment adapted to oscillate the rock-shaft of the oscillating thread-hook, this segment being also shown in Fig. 10. Fig. 12, Sheet 9, is a rear elevation, partly in section, showing the oscillating gearing 45 and connections for the thread-hook shaft. Fig. 13, Sheet 10, is a front elevation of the stitch-forming mechanism, showing the bobbin in position and the thread-hook just entering the loop of machine-thread in the operation of forming a stitch and showing the 50 bobbin-bracket in dotted lines. Fig. 14, Sheet 10, is a similar view to Fig. 13, but showing the thread-hook in its most advanced position in the next step of the operation of forming a stitch, the thread-loop being delivered from the needle and caught over the nose of the hook and in the bight thereof. Fig. 55 15, Sheet 10, is a similar view to Fig. 14, but showing the thread-hook on its retreating 60 movement, carrying the thread-loop with it and drawing it out over the bobbin, and also showing the operation of the spreading-finger in lifting the thread from the point of the hook. Fig. 16, Sheet 10, is a similar view to 65 Fig. 15, showing a succeeding point of the operation of forming a stitch, the thread-loop having been carried clean over the bobbin

and dropped from the hook, the tail of the latter shielding the point of the needle from becoming entangled with the said thread-loop. 70 Fig. 17, Sheet 10, is a similar view to Fig. 16, but showing a succeeding point in the operation of forming a stitch, the loop being shown in the course of being drawn up by the take-up mechanism and the tail-shield of the hook 75 still guarding the point of the needle. Fig. 18, Sheet 9, is a central vertical transverse section through the thread-hook block and the mechanism carried thereby looking toward the right, the parts being in the position shown in Fig. 20 and the bobbin and bobbin-bracket being shown in dotted lines for clearness of illustration. Fig. 19, Sheet 9, is a similar view to Fig. 18, but illustrating the thread-hook in a more advanced position 80 on its retreating movement than Fig. 18, so that the section is taken through the waist of the thread-hook and through the center of its supporting-arm. This figure illustrates also the action of the spreading-finger. Fig. 20, 90 Sheet 9, is a front view of the thread-hook block and the parts mounted therein, shown in nearly the same position as in Fig. 15, the bobbin and its bracket being removed and the right of the block being shown in section to illustrate the spreading-finger and its 95 shaft. Fig. 21, Sheet 11, is a central vertical transverse section of the thread-hook block and the stitch-forming mechanism carried thereby looking toward the left, all the parts 100 being shown in full lines and the position of the thread-hook being the same as that shown in Fig. 14. Fig. 22, Sheet 11, is a similar view to Fig. 21, but showing the parts in the same position as that shown in Fig. 16. Fig. 23, 105 Sheet 11, is a perspective view of the bobbin-bracket from the front side thereof. Fig. 24, Sheet 11, is a similar view of the bobbin-bracket from the rear side. Fig. 25, Sheet 8, is a sectional view showing the means of 110 adjusting the bobbin-bracket to afford a requisite space play for the bobbin-case. Fig. 26, Sheet 11, is a perspective view of the part constituting the thread-hook shaft, gear, disk, and arm, the thread-hook being indicated in 115 dotted lines. Fig. 27, Sheet 5, is a perspective view of the back plate separating the bobbin-case from the thread-hook, disk, and arm and forming the back plate of the bobbin-box. Figs. 28 and 29, Sheet 10, are perspective views taken, respectively, from the front and rear sides of the preferred form of my oscillating thread-hook. Fig. 30, Sheet 4, is a perspective view from the front side of a modified form of thread-hook. Fig. 31, Sheet 125 5, is a perspective view from the rear side of the thread-hook shown in Fig. 30. Fig. 32, Sheet 12, is a front elevation of the bobbin and bobbin-case. Fig. 33, Sheet 12, is a vertical central section through the same in a 130 plane parallel to Fig. 32. Fig. 34, Sheet 9, is a central vertical transverse section through the bobbin and bobbin-case. Fig. 35, Sheet 12, is a perspective view of the bobbin. Fig.

36, Sheet 13, is a perspective view from the right front upper corner of the machine of the spreading-finger and its operating mechanism *in situ*, the supporting parts therefor being shown in dotted lines. Fig. 37, Sheet 13, is a side elevation of the shoulder-bolt forming the pivot for the spreading-finger cam-lever. Fig. 38, Sheet 13, is a perspective view of the bracket forming the support for the pivot-bolt shown in Fig. 37. Fig. 39, Sheet 9, is a perspective view of the spreading-finger cam-lever in the form thereof shown in Fig. 36 and the other figures heretofore described. Fig. 40, Sheet 11, is a perspective view of the spreading-finger. Fig. 41, Sheet 13, is a side elevation from the right of the machine, showing a modified arrangement of the spreading-finger-operating mechanism. Fig. 42, Sheet 7, is a perspective view of the modified form of spreading-finger cam-lever shown in elevation in Fig. 41. Fig. 43, Sheet 12, is a perspective view of the operating parts of my improved work-gage adjustment *in situ*, the stationary parts and the carriage in which they are mounted being indicated in dotted lines. Fig. 44, Sheet 12, is a perspective view showing the parts of the work-gage-adjusting device mounted on the adjusting-shaft, these parts being shown in separated positions. Fig. 45, Sheet 12, is a perspective view of the block in which the work-gage-adjusting shaft is mounted to turn. Fig. 46, Sheet 12, is a perspective view of the tangent screw-stop adapted to regulate the movements of the shaft of the work-gage-adjusting mechanism. Fig. 47, Sheet 14, is a perspective view of the feed-carriage, showing the work-gage, presser-foot, slotted guide-block, and other correlated parts in position thereon. Fig. 48, Sheet 14, is a similar view showing the feed-carriage by itself. Fig. 49, Sheet 14, is a front-to-rear sectional elevation taken on the line 49 49 of Fig. 1 looking toward the left, showing the feed-carriage and its cam-lever and the stitch-regulating mechanism in section. Fig. 50, Sheet 14, is a perspective view of the work-gage from the rear left-hand side thereof. Fig. 51, Sheet 14, is a perspective view of the work-gage pinion and its shaft. Fig. 52, Sheet 14, is a perspective view of the presser-foot and presser-foot bar. Fig. 53, Sheet 14, is a perspective view of the eccentric bolt forming the pivot for the feed-lever. Fig. 54, Sheet 14, is a perspective view of the slide-block connecting the feed-lever through the stitch-regulating mechanism to the carriage. Fig. 55, Sheet 15, is a perspective view of the table-bracket, thread-measuring device, and connecting parts *in situ*, the stationary parts of the machine being indicated in dotted lines. Fig. 56, Sheet 15, is a perspective view of the table-bracket and the work-table in position thereon. Fig. 57, Sheet 16, is a plan of the thread-measuring, pull-off, lock-regulating, thread-lock, and tension devices, parts of the machine being shown in section and the main shaft and its connected

devices being removed. Fig. 58, Sheet 16, is a front-to-rear sectional elevation taken on the line 58 58 of Fig. 57, parts being shown broken away. Fig. 59, Sheet 16, is a front elevation of the parts shown in Fig. 57, parts being shown broken away. Fig. 60, Sheet 16, is a perspective view of the thread-measuring arm. Fig. 61, Sheet 7, is a central plan section taken on the line 61 61 of Figs. 2 and 58. Fig. 62, Sheet 15, is a perspective view of the table-locking block. Fig. 63, Sheet 15, is a similar view of the guide-bracket for the table-locking block. Fig. 64, Sheet 15, is a perspective view of the thread-measuring truck and awl cam-roller, showing the awl-lever in dotted lines. Fig. 65, Sheet 15, is a perspective view of the guide for the thread-measuring truck. Fig. 66, Sheet 15, is a central vertical section through the thread-measuring truck, taken in a plane at right angles to the section shown in Fig. 5. Fig. 67, Sheet 15, is a perspective view of the lock-regulating device. 90

The same characters of reference denote like parts in all the figures of the drawings.

The machine as a whole consists in a supporting base or frame having a pair of posts forming bearing-supports for the main shaft, 95 located at the respective sides thereof, a divided work-head rising from the front portion of the plate, and a cam-lever pivot-arm from the rear end, a series of cams mounted to turn on the said main shaft, cam-levers co-operating with the cams pivoted at various points on the frame and movable parts of the machine, stitch-forming mechanism carried at the front portion of the frame upon and by and in co-operation with the said work-head, and various adjunctive devices for perfecting the operation of the machine and adapting it to perform stitching-work of various dimensions, lengths of stitches, thickness of seam, and the like, according as may 100 be desired.

The various functions of the machine so far as they relate to the moving parts may be grouped under the following heads—that is to say, first, the awl-motion, which serves to 115 perforate the hole in preparation for the insertion of the needle therethrough in the formation of a stitch; second, the needle-motion, which serves to insert the needle into the hole prepared for it by the awl and to draw 120 the machine-thread therethrough; third, the looper-motion, which performs the operation of carrying the machine-thread around the barb of the needle to form the loop which is carried up by the needle; fourth, the thread-hook motion, which takes the place of the shuttle-motion of former stitchers and which serves to take the loop of machine-thread from the needle and carry it around the bobbin; fifth, the take-up motion, which serves 125 to draw down the loop of machine-thread after it has been carried around the bobbin and pull it taut in proper position in the seam; sixth, the feed-motion, which serves to ad-

vance the work after the completion of the stitch and to carry it into position ready for the formation of the next stitch, and, seventh, the pull-off motion, which serves to draw from the wax-pot through the tension mechanism the proper amount of thread required for the formation of each stitch. In addition to these several motions may be mentioned as adjunctive devices assisting in the work of stitching, eighth, the measuring device, which serves to increase or diminish the amount of thread drawn out by the pull-off mechanism, according to the thickness of the seam, and, ninth, the lock-regulating device, which is a manual adjustment serving to position the lock in the work at the distance between the faces of the seam which may be required.

To perform the various motions above related, twelve cams are necessary in the present form of the machine—to wit, the following, enumerated in the order in which they are arranged, beginning at the left of the machine and passing successively to the right: first, the thread - hook cam, (herein designated as H;) second, the looper - cam, which is in reality a double cam formed of two separate cams coating to produce a circular motion, (designated as L;) third, the needle-guide cam, (designated as G;) fourth, the thread-finger cam, (designated as M;) fifth, the needle-cam, (designated as N;) sixth, the awl-cam, (designated as A;) seventh, the presser-foot cam, (designated as P;) eighth, the thread-lock cam, (designated as V;) ninth, the take-up cam, (designated as T;) tenth, the table-lock cam, (designated as W;) eleventh, the feed-cam, (designated as F,) and, twelfth, the spreading-finger cam, (designated as S.) Most of these cams—that is to say, the exterior or surface cams—are visible in the plan view, Fig. 1. The remainder—that is to say, the grooved cams—are shown either in full or dotted lines in one or more of Figs. 2, 3, 4, 5, and 6. With each of these cams coöperates its appropriate lever, which levers are designated herein by the same reference characters as the cams, followed by the numeral "1"—that is to say, H¹ designates the thread-hook cam-lever, (shown in Figs. 1, 2, 3, and 6;) L¹, the looper-lever, (shown in Figs. 1, 2, 3, and 6;) G¹, the needle-guide cam-lever, (shown in Figs. 3 and 6 dotted;) M¹, the thread-finger cam-lever, (shown in Figs. 1, 3, and 6;) N¹, the needle-lever, (shown in Figs. 1 and 6;) A¹, the awl-lever, (shown in Figs. 1, 2, and 5;) P¹, the presser-foot lever, (shown in Figs. 1 and 5;) V¹, the thread-lock lever, (shown in Figs. 1, 3, 4, and 5;) T¹, the take-up lever, (shown in Figs. 1, 4, and 5;) W¹, the table-locking lever, (shown in Figs. 4 and 5 dotted;) F¹, the feed-lever, (shown in Figs. 1, 2, 4, and 5,) and S¹ the spreading-finger lever. (Shown in Figs. 1, 4, and 5 dotted.) The figures hereinabove catalogued as showing the levers are simply those showing the views of the assembled machine, other views being also provided for a clearer understanding of their respective arrange-

ments, as will be hereinafter referred to. These cams and their levers perform, directly or indirectly, all the operative motions of the machine and may be grouped according to the seven different motions above catalogued, as follows: A single cam (the awl-cam) is necessary for the awl-motion, two (the needle and needle-guide cams) for the needle-motion, two (the looper and thread-finger cams) for the looper-motion, two (the thread-hook and spreading - finger cams) for the thread-hook motion, two (the thread-locking and take-up cams) for the take-up motion, three (the presser-foot, table-locking, and feed cams) for the feed-motion, and no separate cam for the pull-off motion, the awl-motion being utilized for this purpose.

In the following detailed description of the machine the following reference nomenclature will be used for convenience sake to designate the various parts, being the same as indicated in the above designation of the cams and their levers—that is to say, a capital letter followed by an appropriate numeral is used to designate the parts relating to the respective cam-motions, the letter H being reserved for the thread-hook motion, L for the looper - motion, G for the needle-guide motion, M for the thread-finger motion, N for the needle-motion, A for the awl-motion, P for the presser-foot motion, V for the thread-lock motion, T for the take-up motion, W for the table - locking motion, F for the feed-motion, and S for the spreading-finger motion, and in addition the letter Q, with following numeral, is reserved for the parts relating to the pull-off device, Z for the measuring device, R for the lock-regulating device, and D for the stationary parts constituting the frame, while such unrelated parts as do not properly belong to either of the above classes are designated by common reference-numerals.

In order to understand clearly the construction and mode of assembling the machine, reference should first be had to Sheet 7, in particular to Figs. 7, 8, and 9 thereof, which show the structure of the frame. This frame is shown as a whole in Fig. 8, (a part on the right being broken away, this part being shown in other views—as, for instance, Figs. 1 and 3,) and this frame consists, substantially, of seven castings, designated, respectively, as D¹, D², D³, D⁴, D⁵, D⁶, and D⁷. The casting D¹ is shown by itself in side and front elevations in Figs. 7 and 9, this casting consisting, substantially, of a base-plate D⁶ of approximately cross shape, having lateral arms D⁷ and D⁸, adapted for the securing of the castings D² and D³, respectively, and front and rear limbs D⁹ and D¹⁰, which serve, respectively, for the support of a divided work-head D¹¹ and of the upright post D⁴. The work-head D¹¹ is in the form of two obliquely forwardly extending posts D¹² D¹³, rising approximately in parallel relation and leaving a parallel-sided opening D¹⁴ between them, in

which space is mounted the needle and awl mechanism and into which depends likewise the presser-foot limb of the feed-carriage and the parts mounted thereon. The left-hand 5 post D¹² has a depending lug D¹⁵ projecting therefrom to form the pivot of the thread-finger, as will be hereinafter described, and it also carries other lugs and holes bored therethrough, which will be hereinafter more 10 completely described in relating the parts with which the said holes and lugs are intended to coöperate. The right-hand post D¹³ of the work-head D¹¹ carries projecting laterally from its upper end a block D¹⁶, which is provided with a planed upper face D¹⁷, Fig. 8, and a longitudinal channel D¹⁸ for the reception of the reciprocating feed-carriage. Directly in front of the post D¹³ is formed upon the base-plate D⁶ a projecting pivot-lug D¹⁹, adapted to 15 form means for sustaining the auxiliary and take-up arms in a manner which will be herein-after described, this pivot-lug being strengthened by a web D²⁰, connecting it with the post D¹³. This right-hand post D¹³ is furthermore 20 provided with other lugs, projections, conformations, and holes, which are destined to receive the separate parts and will be herein-after described when speaking of the parts coacting therewith. The base-plate D⁶ has 25 ribbed bosses D²¹, D²², and D²³ thereon, which are planed to receive the lower faces of the posts D², D³, and D⁴, respectively, and a pair of bolt-holes D²⁴ are shown for clamping the base-plate D⁶ to its pedestal. A planed boss 30 D²⁵ is also shown just to the right of the post D¹³ of the work-head, this being adapted to form a sliding surface for the locking-block. The other parts and conformations of the base-plate D⁶ will be hereinafter described. 35 The two posts D² and D³ (shown in Fig. 8) are destined to support the respective ends of the main shaft, being provided with bearing-apertures D²⁶ for this purpose. The post D² is, moreover, branched at its upper end, 40 having a rearwardly-extending arm D²⁷, adapted to support the thread-hook cam-lever, and a forwardly-extending arm D²⁸, which is bent at right angles, as shown at D²⁹, and secured at its end upon a horizontal surface D³⁰, 45 formed upon the post D¹² and secured thereto by a screw D³¹, the purpose of the arm D²⁸ being to strengthen the frame by mutually connecting the post and work-head. From the upper side of the arm D²⁸, close to the 50 head D³² thereof, which is seated upon the rest D³⁰, rises an upstanding lug D³³, which is destined for the adjustable attachment of the casting D⁵ by means of a single bolt D³⁵, passing through both pieces, whereby the casting D⁵ is adapted to have a slight pivotal adjustment, this being found to be necessary in properly assembling the machine. The casting D⁵ is a bracket-casting having an obliquely forwardly-extending horizontal arm 55 D³⁶, which is provided with means for attaching springs thereto, this bracket being intended to support the springs of the needle- 60

guide and thread-finger cams, respectively. The opposite bearing-post D³ of the frame is likewise joined to the block D¹⁶ of the post D¹³ of the work-head by means of an arm D³⁷, which, as herein shown, is separately cast and driven over a cylindrical sleeve on the inner side of the post D³ or which may be secured thereto in any other suitable manner, 75 while its forward end is connected by a bolt D³⁸ to the end of the block D¹⁶ and has midway thereof an upstanding lug D³⁹ for supporting the spreading-finger-cam lever. The rear post D⁴ of the frame is provided with 80 bearing-bosses D⁴⁰ D⁴¹, respectively, at the upper and near the lower end of the post, the upper of which supports the bolt carrying the needle and take-up levers N¹ and T¹, Fig. 1, and the lower boss D⁴¹ carries the bolt forming the 85 axis of the awl and thread-lock levers A¹ and V¹, Figs. 4 and 5. The several posts D², D³, and D⁴ are respectively secured to the base-plate D⁶ by means of bolts D⁴², D⁴³, and D⁴⁴. 90 In addition to the bracket-casting D⁵ the arm D²⁸ of the post D² also carries bolted thereto at a point to the left of the lug D³³ and close to the elbow D²⁹ an upstanding slotted casting D⁴⁵, which is secured to the arm D²⁸ by means of screws D⁴⁶ and is provided with a 95 vertical front-to-rear slot D⁴⁷ therein, extending nearly the entire length of the casting, this slot being intended as a guide for the front end of the thread-hook cam-lever H¹, as seen in Figs. 1 and 2 and as will be herein- 100 after referred to. 105 In the assembled position of the machine as operated, Figs. 1 to 6, the frame is shown as mounted upon a pedestal 68 and secured thereto by bolts 69, passing through the bolt-holes D²⁴ in the base-plate, and is provided with the usual apparatus for heating the machine by means of a gas-flame within the hollow pedestal, a swinging hot-air door for the forward portions of the machine being shown 110 at 70 mounted upon a hinge-block 70^a. 115 Supported by the posts D² and D³ of the frame and in the bearings D²⁶ is the main shaft 71, this shaft extending, as usual, to the left of the post D² and provided on its left-hand end with an overhung balance-wheel 72, which is grooved, as shown at 73, for the reception of a power-belt adapted to operate the machine. The shaft 71 is provided between the two bearings D²⁶ with a longitudinal key or feather 74, extending practically the entire distance, which coöperates with the cam-blocks mounted on the shaft to keep them from rotating thereon. These cam-blocks are designated in order from left to right as 75, 76, 77, and 78, the first of which, 75, is provided with a thread-hook cam formed as a groove in its right-hand or inner face. (See Fig. 10.) The second cam-block 76 carries four or, more properly, five cams—that is to say, the looper, 120 needle-guide, thread-finger, and needle cams—the double-looper cam L consisting, as usual, of a surface and a grooved cam (shown, respectively, in Figs. 1 and 3) of the ordinary 125 130

type on the left-hand face of the block, the needle-guide and thread-finger cams G and M, Figs. 1 and 3, as surface cams on the exterior or cylindrical surface of the block, and 5 the needle-cam N, Fig. 6, as a grooved cam on the right-hand face of the block. The cam-block 77 is provided with three cams—that is to say, the awl-cam A, Fig. 5, formed as a grooved cam on the left-hand face of the 10 block, the presser-foot cam P, Figs. 1 and 5, as a surface cam on the cylindrical face of the block, and the thread-lock cam V, Figs. 1, 4, and 5, formed as a very small surface cam around the cylindrical surface of the 15 hub of the block. The cam-block 78 is provided with four cams—that is to say, the take-up cam formed as a grooved cam on the left-hand face of the block, the table-locking cam W, Figs. 1, 4, and 5, formed as a 20 surface cam on the cylindrical exterior surface of the block, the feed-cam F, Fig. 1, formed as a grooved cam in the cylindrical surface of the block, as shown, and the spreading-finger cam S, Figs. 4 and 5, formed as a grooved cam 25 in the right-hand face of the block. All these cams turn with the shaft 71, as shown, in a backward direction—that is to say, a left-handed direction—as seen from the left of the machine.

30 *The thread-hook motion.*—I will now describe in order the several motions constituting the machine, in which description it will successively appear which parts are of my invention, beginning with the thread-hook cam 35 or stitching motion, which is operated by the cam H and the cam-lever H¹. These parts are shown in perspective view in Fig. 10, the lever H¹ being pivoted, as above referred to, upon the rearwardly-extending arm D²⁷ of 40 the post D² of the frame, and upon a pivot-bolt or stud H². The lever H¹ is of course provided with a trundle-roller H³, pivoted upon the bolt H⁴ and extending into the groove H, which is of the shape shown, being 45 circular for more than half of its entire length, whereby the thread-hook, to be hereinafter described, is caused to remain stationary the greater part of the time. The cam-lever H¹ is guided at its front end by the sides of the 50 slot D⁴⁷ in the casting D⁴⁵, provided for this purpose, as hereinbefore described, (see Figs. 1, 2, 3, and 6,) and its extremity projects beyond this casting and is provided with a pivot-boss H⁵, in which is pivotally mounted 55 a forked bolt H⁶, secured loosely in the boss H⁵ by means of lock-nuts H⁷ at the left-hand end and at the right-hand end provided with two parallel lugs or flanges H⁸, between which is pivotally mounted a short link H⁹ upon the 60 pivot-pin H¹⁰. The upper end of the link H⁹ is similarly connected by a short pivot-pin H¹¹ between the flanges H¹² of a forked bolt H¹³, which is pivotally secured by means of lock-nuts H¹⁴ within the pivot-boss H¹⁵ of a 65 rock-arm H¹⁶, which is provided with a hub H¹⁷, loosely turning on the axle-bolt H¹⁸, which passes through an aperture in the up-

standing lug H¹⁹, formed centrally on the upper side of the thread-hook block H²⁰, and is secured therein by a nut H²¹. (See Figs. 18 70 to 22, inclusive.) The piece H¹⁶ is shown in perspective in Fig. 11 and carries depending therefrom a gear-segment H²², which intermeshes with a small pinion H²³, which is hidden from view in Fig. 10, but is clearly shown 75 in Figs. 5, 6, 12, 18, 19, 21, and 22. This pinion H²³ is formed upon the thread-hook arbor H²⁴, which is mounted to oscillate on an axis perpendicular to the front face of the thread-hook block and is carried in a bearing-lug 80 H²⁵, recessed, as at H²⁶, to receive the pinion H²³ and secured in its position by means of a pair of lock-nuts H²⁷ and H²⁸. From the above description it will be seen that the connection of the cam H with the arbor H²⁴ will cause it 85 to oscillate at predetermined times in the manner to be hereinafter described.

The thread-hook block, which heretofore performed the function of a shuttle-block and is of a similar general shape to that heretofore used for that purpose, is shown by itself in front elevation in Fig. 20, in rear elevation in Fig. 12, and in central vertical transverse section in Figs. 5, 6, 18, 19, 21, and 22. It is also to be seen as mounted in the front central part 95 of the machine and at the upper portion of the work-head in the front view of the machine in Fig. 2 and is shown in plan in Fig. 1 and in side elevation, respectively, from the left and right sides in Figs. 3 and 4. This 100 thread-hook block is secured by means of three bolts to the posts D¹² and D¹³ of the frame forming the work-head D¹¹, one of the securing-bolts being shown at H²⁹ as set in flush with the face of the block in a recess 105 H³⁰, the bolt-hole in the work-head which receives this bolt being shown at D⁴⁸ in Fig. 9 and immediately over it a smaller hole D⁴⁹ to receive a dowel-pin H³¹, Figs. 10 and 12, projecting from the rear face of the thread-hook 110 block. A similar pair of holes D⁵⁰ and D⁵¹ are provided in the other post D¹² to receive a similar bolt (which is hidden beneath the thread-hook in Fig. 2) and a dowel-pin H³², Figs. 10 and 12, and a third bolt H³³ (shown 115 in dotted lines in Fig. 12) passes sidewise through a hole D⁵² in the post D¹² into the flattened side H³⁴ of the bearing-lug H²⁵.

The thread-hook block H²⁰ is provided in its front face with a shallow cylindrical recess 120 H³⁵, which forms both the bobbin-box and the raceway for the arcuate thread-hook H³⁶, which is adapted to reciprocate around the outer margin of the recess H³⁵, as shown in Fig. 2 and Figs. 13 to 22, inclusive. This 125 thread-hook is itself shown in perspective detail in Figs. 28 and 29, and consists, substantially, of a forward or toe portion H³⁷, a waist portion H³⁸, and a rear or tail portion H³⁹. The part H³⁷ is pointed, as shown at H⁴⁰, this 130 point in the form shown in Figs. 28 and 29 being not rounded like an ordinary pin-point, but having a vertical edge H⁴¹, the edge being slightly oblique to a radius, as shown in the

front views, Figs. 13 to 17, of the thread-hook. Intermediate between the point H^{40} and the waist portion H^{38} is formed a recurved nose or bill H^{42} , having a bight H^{43} , in which the thread-loop is adapted to be caught and held, the inside of the bight H^{43} being convexly rounded, so as to permit easy slipping of the thread therethrough in drawing out the loop. The waist portion of the hook in the form shown is of rectangular section and provided with a recess H^{44} , having approximately vertical sides H^{45} and a pair of screw-threaded apertures H^{46} , this waist portion and the recess thereof being destined to receive and be secured to the broadened extremity H^{47} of the thread-hook arm H^{48} . (Shown in enlarged detail in Fig. 26.) This arm has an axially-extending flange H^{49} and a pair of radially-extending flanges H^{50} , extending therefrom and adapted to coöperate with the surfaces H^{45} of the hook in the manner illustrated in Fig. 26, (the hook being indicated in dotted lines,) and the two parts are secured together by means of screws H^{51} . Returning to Figs. 28 and 29, it will be seen that the tail H^{39} of the hook is provided with a rear exterior groove H^{52} , formed by a radially-extending flange H^{53} and an axial or cylindrical flange H^{54} , these two flanges together being adapted to form a shield to cover the needle when the hook is in the positions shown in Figs. 16 and 17 and to prevent the thread-loop from becoming entangled therewith during the process of drawing down said thread-loop in the manner which will be hereinafter described. The said tail portion H^{39} is, moreover, not formed square at its ends, but is pointed in the manner shown at H^{55} , the point thereof being close to the back of the raceway, so that the said point tends to insert itself beneath the innermost thread of the loop and push it out beyond and out of the way of the needle. This operation will be presently described.

The front portion of the hook is provided in its rear side with a longitudinal groove H^{56} , which tapers off toward the point and becomes gradually deeper as it reaches the nose H^{42} of the hook, this groove performing an important function, as will be hereinafter seen, in receiving the barbed end of the needle and delivering the thread-loop therefrom. The operation of this groove will be presently described.

A slightly-modified form of thread-hook, which was that originally used, is shown in Figs. 30 and 31, Sheets 4 and 5, this thread-hook being designated for convenience H^{136} . This form of hook consists, like that formerly described, of a point portion H^{137} , a waist portion H^{138} , and a tail portion H^{139} , the former being provided with a forwardly-directed point H^{140} and a recurved nose or bill H^{142} . This hook is slenderer than the hook shown in Figs. 28 and 29, especially the bight H^{143} of the hook, and the point H^{140} is of rounded form. In the rear face is formed the groove H^{156} , which is of similar form to that shown

in Fig. 29, but instead of ending at the waist is carried entirely around, so as to be continuous with the tail-groove H^{152} , although it will be understood, of course, that the central portion of this groove does not serve any useful purpose, as the needle does not enter therein, but merely facilitates the process of formation of the hook. The two flanges H^{153} and H^{154} of the tail-shield are in this case nearly parallel, and both of their points H^{155} are tapered and backwardly directed, as shown in Fig. 30. The waist portion of this hook is adapted for a slightly different form of end of the thread-hook arm from that shown at H^{47} in Figs. 13 to 17, being provided with a single screw-hole H^{146} and two dowel-pins H^{147} on opposite sides thereof.

In addition to the thread-hook arm H^{48} , which proceeds radially from the forward extremity of the shaft H^{24} to carry the thread-hook around the raceway H^{35} in the manner above mentioned, I also preferably provide a backing or disk H^{57} , which is in the same plane with the thread-hook arm H^{48} and closes the back of the raceway. This disk is provided with a marginal upstanding flange H^{58} and with a central boss H^{59} , both of which coöperate with the corresponding form of a back plate H^{60} in the manner shown in Figs. 18, 19, and 20. The back plate H^{60} covers the face of the disk H^{57} and forms a stationary backing for the bobbin, this being practically necessary in order to prevent frictional rolling of the thread between the bobbin-case and the oscillating disk H^{57} during the passage of the thread over the bobbin. The back plate H^{60} is shown in detailed perspective view in Fig. 27, Sheet 5, as having a slight marginal flange H^{61} and a central aperture H^{62} , which latter receives and fits over the boss H^{59} on the end of the rock-shaft, and this assists in holding the back plate H^{60} in place. The back plate H^{60} is supported by means of a recessed supporting-tab H^{63} , which has screw-holes H^{64} , through which pass screws H^{65} , securing it firmly to the face of the recess or raceway H^{35} , and a portion of the tab H^{63} is cut away at its junction with the back plate, as shown at H^{66} , to provide a groove, into which the thread-hook arm H^{48} is projected at the extremity of its receding travel, as shown in Figs. 16 and 17. This construction will therefore be seen to practically shield the thread-loop from becoming caught in the oscillating thread-hook arm, which is behind the plate H^{60} , and inasmuch as the space behind the plate H^{60} is entirely closed by the flanged disk H^{57} the thread cannot become engaged behind the back plate H^{60} or tangled therewith.

In the drawings, as shown particularly in Fig. 26, I have shown one side of the disk H^{57} as cut away to form a triangular notch H^{67} in order to leave more room for the needle-block N^4 , which is adapted to be projected thereinto in the manner indicated in Fig. 18.

I will now describe the construction and

mode of support of the bobbin-case and correlated parts, which are herein designated by the letter B followed by a numeral. The bobbin and its case are shown separately in Figs. 32 to 35, inclusive, and in position in Figs. 13 to 17, inclusive, and Figs. 21 and 22. The bobbin alone is shown in Fig. 35 and is designated by the character B¹, while the case is designated B². The bobbin is of the ordinary spool shape, having a central cylindrical hub B³, having at each end thereof radial flanges B⁴. The hub is internally cylindrical and provided with a keyway or groove B⁵, while the flange B⁴ at the front side is annularly recessed, as shown at B⁶. The bobbin-case B² (best shown in Figs. 32, 33, and 34) has a flat back plate B⁷ and an elbowed rim B⁸, which projects centrally to form a rounded edge B⁹, and the front edge of the rim B⁸, as shown at B¹⁰, is made of a diameter just sufficient to enable the bobbin B¹ to be inserted therethrough and the front head or flange B⁴ of the latter to close the opening in the front of the bobbin-case.

At the center of the back plate B⁷ of the bobbin-case is formed a cylindrical socketed boss B¹¹, which is internally screw-threaded to receive the threaded stud B¹², formed on the end of the stationary post B¹³, which supports the bobbin in rotatable position thereon. The post B¹³ is formed cylindrical and of the same diameter as the external surface of the boss B¹¹; but it has near the outer end thereof a head B¹⁴, which forms a rectangular shoulder B¹⁵ with the shank of the post. Over the shank of the post is mounted a cylindrical sleeve B¹⁶, which is fitted to turn easily on the post B¹³ and is exteriorly of just sufficient diameter to receive easily the hub of the bobbin B¹, which is adapted to be slid thereover. The sleeve B¹⁶ has, moreover, an axial rib or feather B¹⁷, which enters the groove B⁵ when the bobbin is in position, and thus the bobbin while permitted to be readily removed from the sleeve when it is desired to take it from the bobbin-case is not rotatable thereon; but the sleeve itself rotates with the bobbin. It will be seen from Fig. 34 that the head B¹⁴ is of a diameter the same as that of the exterior of the sleeve and the post is formed to be flush with the face of the flange B⁴ of the bobbin.

In order to hold the bobbin in position on the post B¹³, I provide a clip B¹⁸, which is seated in the open end of a transverse slot B¹⁹, formed in the head B¹⁴ of the post B¹³, which clip is pivoted on a transverse pintle B²⁰ and is provided with a tongue B²¹, adapted, when in its closed position, to overlie the end of the bobbin-hub and to lie flush in the annular recess B⁶ in the manner indicated in Fig. 34. This clip is provided with a square hub, against which presses a small block B²², which is adapted to reciprocate in a recess B²³ and is kept resiliently pressed against the square hub of the clip B¹⁸ by a coiled spring B²⁴, located back of the block B²² and abutting

against the rear of the recess B²³. It will be thus seen that the tongue B²¹ of the clip is adapted to be held either in radial or axial position in the manner shown in Figs. 13 to 17 and by the dotted lines in Fig. 34.

Inasmuch as the bobbin-case is adapted to remain stationary during the operation of the machine, while the bobbin carrying a coil of bobbin-thread B²⁵ rotates therein, it is desirable to provide means for preventing the unnecessary unwinding of thread caused by the sudden jerk occasioned by the pull up of the thread-loop by the take-up motion and which would cause the stitches to become loose, and I therefore provide tension mechanism for the bobbin-thread comprising a spider-shaped spring B²⁶, which has a central disk surrounding the boss B¹¹, and two or more radial legs B²⁷, which are adapted to press against the back plate B⁷ of the bobbin-case, whereby the central disk or hub of the spring is caused to press outwardly against the sleeve B¹⁶ and produce the necessary amount of friction against the rotation of the bobbin to hold the bobbin-thread taut. It will be observed that the spring B²⁶ is in no wise affected by the removal of the bobbin itself from its case, which is simply accomplished by raising the clip B¹⁸.

The bobbin-case is loosely supported in a box formed by the flanged back plate H⁶⁰ and a bobbin-bracket B²⁸, which is of the form shown in detail in Figs. 23 and 24 and is adapted to be clamped in position upon the thread-hook block H²⁰, as indicated in Figs. 13 to 19, inclusive, in dotted lines. The bobbin-bracket is shown in front perspective in Fig. 23 and in rear perspective in Fig. 24 and comprises a pair of lateral securing-lugs B²⁹ and a central depending annular portion B³⁰, which is in the form of a ring of triangular section, as indicated in Figs. 5, 6, 21, and 22. The inner face B³¹ of the ring B³⁰ is of conical form, corresponding to the conical surface of the bobbin-case, and at its lower edge it is provided with a transverse nick B³², which engages a depending lip B³³ in the front of the bobbin-case at its lower side and prevents it from rotating. Immediately behind the lip B³³ a hole B³⁴ is formed in the bobbin-case for the passage of the bobbin-thread B²⁵. The case is thus held loosely when the bobbin-bracket is in position between the back plate H⁶⁰ and the bracket, having a certain amount of play therein sufficient for the passage of the thread-loop on both sides of the case.

In order to properly adjust the bobbin-bracket in position, the following securing means are adopted: The thread-hook block is provided with a pair of bosses H⁶⁸ H⁶⁹, which have central apertures H⁷⁰ H⁷¹ corresponding with the bolt-holes B³⁵, formed in the ends of the lugs B²⁹. The left-hand hole H⁷⁰ is threaded for the reception of a stud B³⁶. The right-hand aperture H⁷¹ is preferably not threaded, but left smooth for the reception of the cylindrical shank B³⁷ and a stud B³⁸, whose for-

ward end only is screw-threaded, as shown at B³⁹, Fig. 25, Sheet 8. The stud B³⁷ is clamped in position in the aperture H⁷¹ by a set-screw H⁷², Fig. 20, the side of the thread-hook block being bored for this purpose. Over both of the studs B³⁶ B³⁸ are placed adjusting-nuts B⁴⁰, having cylindrical sides and radial apertures B⁴¹, through which a pin may be inserted to turn the nut, and these nuts B⁴⁰ underlie the bolt-lugs B²⁹, which are set forwardly on the body of the bobbin-bracket, as shown in Figs. 23 and 24, and over the lugs B²⁹ are placed ordinary nuts B⁴², so that the bobbin-bracket is clamped between the two pairs of nuts B⁴⁰ B⁴², and its position upon the stud may be regulated by turning the adjusting-nut B⁴⁰, thus enabling the exact amount of play proper for the bobbin-case to be secured.

20 The spreading-finger motion.—The motion now to be described is really a part of the stitching mechanism, coacting closely with the operation of the thread-hook and being intended especially for this species of stitcher, 25 although it is not a necessary part of my machine, but enables the stitching to be carried on more advantageously. The spreading-finger mechanism is operated by means of the cam S on the extreme right of the machine, said cam being clearly illustrated in Fig. 4 of the drawings, while the moving parts constituting the mechanism are illustrated in perspective in Fig. 36, the stationary parts to which they are attached being 30 shown in dotted lines. The cam S, as shown, is circular throughout its entire extent, with the exception of a small arc shown at the upper right-hand side in Fig. 36, which comprises two slightly inwardly bent curves S² and S³ and an outwardly-bent curve, of nearly the same extent, S⁴, between them, this conformation serving to give the spreading-finger S⁵ a species of vibration first forwardly, then backwardly, then forwardly again from 35 its central position in which it is shown in Fig. 36. The spreading-finger alone is illustrated in perspective in Fig. 40, Sheet 11, its extreme positions being indicated in dotted lines.

50 The cam-lever S¹ has a roller S⁶, extending within the cam-groove S, and a long pivot-hub S⁷, which is mounted to rock on a double-shouldered screw S⁸, Fig. 37, having a polygonal head S⁹, an enlarged shank portion S¹⁰, a reduced shank portion S¹¹, and a screw-threaded stud S¹². The enlarged portion S¹⁰ of the shank is seated in an aperture D⁶³ of the upstanding lug D³⁹ of the bracket D³⁷, Fig. 8, while the stud S¹² of the bolt is screwed 55 into an internally-threaded aperture S¹³, formed in a block S¹⁴, which is of angular form, as shown in Fig. 38, and is adapted to be seated over the rear upper corner D⁶⁴ of the block D¹⁶ of the frame, Fig. 8, and to be 60 secured thereto by suitable bolts passing through the apertures S¹⁵ and S¹⁶, formed, respectively, in the side and top of the block

and through corresponding apertures D⁶⁵ and D⁶⁶ in the block D¹⁶. The shank portion S¹¹ of the bolt S⁸ is of the same length as the hub S⁷ of the cam-lever and adapted to pivotally support the latter.

As will be seen from the perspective view of the cam-lever S¹ shown in Fig. 39, the arm carrying the roller S⁶ is on the right-hand or outer end of the hub S⁷, while its inner or left-hand end has a second depending arm S¹⁷ nearly at right angles to the arm S¹, and which arm is adapted to oscillate opposite the face of the cam-block 78 and in a notch 80 or recess D⁶⁷, formed in the rear face of the block D¹⁶ for this purpose. The lower end of this arm S¹⁷ is pivotally connected by a pivot-screw S¹⁸ with a link S¹⁹, which passes beneath the block D¹⁶ and is connected at its 85 forward end by a pivot-screw S²⁰ with a rock-arm S²¹, which is clamped upon the outer end of the spreading-finger rock-shaft S²² by a set-screw S²³. As is indicated by the dotted lines in Fig. 36, the rock-shaft S²² is mounted 90 to oscillate in an aperture H⁷³, covering the entire length of the rock-shaft and bored longitudinally in the thread-hook block H²⁰, as indicated in Fig. 20, and the block H²⁰ may be provided with an oil-conduit H⁷⁴, Figs. 1 95 and 20, leading from the upper flat surface H⁷⁵ of the notched portion on the right hand thereof to the aperture H⁷³. The inner or left-hand end of the rock-shaft S²² carries the depending spreading-finger S⁵, which is of 100 arcuate form, approximately concentric with the thread-hook shaft H²⁴ and is located in a hollowed-out recess or niche H⁷⁶, formed in the lateral face of the recess H³⁵, and is adapted to have a slight oscillating motion there- 105 in. The spreading-finger S⁵ follows closely the exterior face of the thread-hook when the latter is in the position shown in Fig. 20 and projects forwardly to the center line of the stitching-motion, so as to be adapted to engage between the two laps of the thread-loop and to be inserted thereto when the latter is drawn back by the thread-hook, and it is during the forward and subsequently retreat- 110 ing motion of the thread-hook that the oscil- 115 lating motion is given to the spreading-finger to spread the laps of the thread-loop and to deliver the latter easily from the point of the hook as the latter passes into the position shown in Fig. 15. This operation will be de- 120 scribed more fully hereinafter in relating the operation of the machine as a whole.

The construction of the spreading-finger mechanism just described by me is that originally used; but I have invented a somewhat 125 improved form having a similar series of parts, but shaped slightly differently, so as to have the disposition and form shown in Fig. 41. The object of this modification was to avoid the difficulty caused to some extent by the po- 130 sitioning of the parts as in Fig. 36, because the link S¹⁹ and the arm S²⁰ projected downwardly and forwardly so far as to be in the way in large stitching operations where heavy

curved pieces of leather were being stitched and would curve up on the right hand of the stitching-head and come into contact with and become engaged by the projecting parts of the spreading-finger mechanism. In Fig. 41 the links and levers are carried over instead of under the block D¹⁶, as will be seen. I herein substitute for the cam-lever S¹ a differently-formed lever S¹⁰¹, having a cam-roller S¹⁰⁶ and a hub-sleeve S¹⁰⁷, pivotally mounted on the bolt S⁸ in the same manner as the lever S⁷. The cam-lever S¹⁰¹ is illustrated in perspective detail in Fig. 42. Instead of the downwardly-projecting arm S¹⁷ there is an upwardly-projecting elbowed arm S¹¹⁷, rising from the left-hand end of the hub-sleeve S¹⁰⁷, which arm is connected by a pivot-screw S¹¹⁸ with a doubly-bent link S¹¹⁹, arranged to overlie the upper side of the block D¹⁶ and of the feed-carriage and the parts carried thereby and to be connected by a pivot-screw S¹²⁰ with the rock-arm S²¹, which, as shown in Fig. 41, is reversed in position, so as to project upwardly instead of downwardly, as in Fig. 36. It will be seen that the cam S is not changed in any way, inasmuch as this connection gives the same motion as that shown in Fig. 36.

The awl, needle, and looper motions.—These motions are with a single exception the same as those in the machine already in use, and a very brief reference to the parts shown on the drawings will therefore be necessary in order to enable the latter to be understood by those skilled in the art. No detailed views of these parts are given, reference being had merely to Figs. 1 to 6, inclusive. The awl-cam is clearly shown at A in Fig. 5, and the lever A¹ therefor is pivoted, as hereinabove referred to, upon a pivot-bolt 79, mounted in the boss D⁴¹ of the rear post D⁴ of the frame, and it carries at its forward end, formed integral therewith, a gear-segment A², which meshes with the pinion-segment A⁴, formed on the awl-block A⁵, to which is secured the awl A⁶, projecting through a slot in the work-table, as usual, and oscillated by means of the awl-lever A¹, while at the same time it receives a reciprocating motion from the feed-carriage, as usual, being pivotally mounted upon a bolt A⁷, carried by the lower end thereof, and as will hereinafter appear. The trundle-roll A⁸, Fig. 64, Sheet 15, which connects the lever with the cam, is mounted on a transverse bolt A⁹, and the latter does not serve simply for this purpose, but also for a support for the pull-off motion, which will be referred to hereinafter, and for this reason the awl-lever herein shown has no rearwardly-extending arm back of its pivot 79.

The needle-lever N¹, Fig. 6, as above described, is mounted to oscillate upon a pivot-bolt 80, carried by the upper boss D⁴⁰ of the rear post D⁴ of the frame, and is best shown in Fig. 6. It carries at its forward end the gear-segment N², which meshes with a pinion-segment N³ on the needle-block N⁴, to which is adjustably clamped the barbed needle N⁵,

and which oscillates upon a pin N⁶, Fig. 3, which is socketed in the aperture D⁵³, formed in a projecting lug D⁵⁴ on the left-hand post D¹² of the work-head, Fig. 7, and has a circumferential head N⁷, Fig. 6, which confines the needle-block. On the left of the needle-block is also mounted a needle-guide G², which embraces the needle forwardly of its point of securing in the needle-block and holds it in line with the work, this needle-guide being also provided with a gear-segment G⁸, meshing with a pinion G⁴, mounted on a short rock-shaft G⁵, which is pivoted in an aperture D⁵⁵ in the post D¹² of the work-head, Fig. 7, and the shaft G⁵ carries on its left-hand end a pinion G⁶, adapted to be adjustably clamped to the shaft G⁵ by lateral lugs G⁷ and a bolt G⁸, all of which are shown in Fig. 3. With this pinion G⁶ meshes a gear-segment G⁹, carried upon the end of a rock-arm G¹⁰, which forms an integral part of the needle-guide cam-lever G¹, the latter being in the form of a bell-crank lever, as shown, pivoted at an intermediate point upon a pivot-bolt G¹¹, mounted in the screw-threaded aperture D⁵⁶, Fig. 7. As the needle-guide cam G is a surface cam, the lever G¹ is held against the surface of the cam by the tension of a spring G¹², whose lower end is connected to the arm G¹⁰ by a pin G¹³ and whose upper end is connected to a laterally-projecting pin D⁵⁷, projecting from the side of the bracket-casting D⁵.

The looper-lever L¹ has a universal pivot (shown at L² in Figs. 2 and 3) at an intermediate point thereof, which is pivotally mounted in the aperture D⁵⁸, Fig. 7, and said lever has two trundle-rolls L³ and L⁴, bearing, respectively, on the surface cam and in the grooved cam, and a bracket-arm L⁵, extending rearwardly and having a hooked finger L⁶, which retains the loop of the U-shaped wire L⁷, connected with a spring-plate L⁸, upon which presses one end of the coiled spring L⁹, mounted upon a bolt L¹⁰, which is connected to the post D⁴, the compression of the spring L⁹ holding the roller L³ against the face of its cam. On the front end of the looper-lever is carried the looper L¹¹, which is of the ordinary type, having a hole through which the machine-thread is passed, and the looper is thus adapted by the motions given it by its double cam to have a circular motion about the head of the needle when the latter is pushed forwardly and downwardly through the hole prepared for it by the awl.

Coöoperating with the looper L¹¹ is the thread-finger M², which is adjustably clamped by a bolt M³ to a bell-crank lever M⁴, which is pivoted upon a pivot-pin M⁵, bolted in an aperture D⁵⁹, formed in the lower end of the depending lug D¹⁵ on the work-head, Fig. 7, and the opposite end of the lever M⁴ is connected by a link M⁶ with a short intermediate lever M⁷, pivoted near its central point upon a pin M⁸, mounted in the aperture D⁶¹ in the work-head, Fig. 7, and connected at its other end

by a link M^9 to a forwardly-projecting arm M^{10} on the thread-finger cam-lever M^1 , which is pivoted upon a pivot-screw M^{11} , screwed into the upstanding lug D^{33} of the frame. The cam-lever M^1 has a trundle-roll M^{12} , which presses against the face of the cam M , being held in operative connection therewith by the pressure of the coiled spring M^{13} , Fig. 6, mounted on a depending post M^{14} , which passes through a hole D^{62} in the horizontal bracket of the casting D^5 and is secured thereto by nuts M^{15} . The post M^{14} passes through a slot M^{16} (indicated in dotted lines in Fig. 1) in the arm M^{10} and has on its lower end a flat circumferential head M^{17} , Fig. 6, between which and the lower side of the arm M^{10} presses the spring M^{13} , thus holding the lever M^1 up to its work. It will be observed that the shape of the cam M is such that it is formed substantially of two circular arcs M^{18} and M^{19} of different radii, joined at their ends by oblique portions M^{20} and M^{21} . During the time that the cam-roller M^{12} is on the circular portion M^{19} the thread-finger will be stationary and, in front of the looper in the position shown in Fig. 6. Just before the looper is caused to take a turn of thread around the needle the cam-roller M^{12} will pass down the inclined surface M^{20} onto the circular surface M^{18} , the thread-finger being caused thereby to draw the thread carried by the looper inwardly, so as to coat with the looper in engaging the loop of thread with the needle. During this time the thread-finger is again stationary and at the rearward limit of its movement; but just before the inclined surface M^{21} is reached to carry the thread-finger outwardly again the surface M^{18} is provided with two successive small lifts M^{22} and M^{23} , which are shown somewhat exaggerated in Fig. 6, the dimensions of these lifts being extremely slight; but they serve a definite purpose in feeding the slight amount of additional thread needed by the needle as it reaches the limit of its upward movement. It will be observed also that in my machine the pivot of the thread-finger is located much farther outwardly and forwardly than in the former type of the machine, so as to be directly under the thread-finger when the latter is in its rearmost position, a change which is needed to coat with the lifts M^{22} and M^{23} and the cam in giving a slight amount of additional thread to the needle and in making more perfect the action thereof.

The take-up motion. — This mechanism comprises two independent cams and their levers, one operated from the block 78 and the other from the block 77—that is to say, the take-up device proper which draws the thread-loop down after it has been drawn around the bobbin and the thread-lock device which holds the rear end of the thread steady, so as to prevent the take-up from drawing the thread from the wax-pot. The take-up lever T^1 is shown in Figs. 1, 4, and 5, being operated from a grooved cam T , Figs. 4 and

5, (dotted,) which is circular during the greater portion of its circumference and has at one point a sharp peak T^2 , which causes the lever to be suddenly thrown upwardly and back again, this operation taking place during the quick retreating movement of the thread-hook while the thread is being drawn around the bobbin. The thread-hook lever T^1 is pivoted upon the same pin 80, carried by the rear post D^4 of the frame, that serves to support also the needle-lever, and it has at an intermediate point a sidewise-projecting trundle-roll T^3 , which engages with the cam-groove T . At its forward end the take-up lever T^1 has pivoted thereto a long depending link T^4 , which passes between the two posts D^{12} D^{13} of the work-head and has a slight bend T^5 near the base of the work-head, as illustrated in Figs. 4 and 5, and is connected at its lower end by a pivot-screw T^6 to the take-up arm T^7 at a short distance forwardly of its pivot upon the bolt T^8 , which is of the form illustrated in Fig. 61, (Sheet 7.) The bolt T^8 has a shouldered shank composed of an enlarged portion T^9 and a reduced portion T^{10} , the former of which forms the pivot for the hub T^{11} of the take-up arm T^7 , the bolt having a head T^{12} , which serves to confine the hub T^{11} , and having the shoulder of the shank T^9 seated against the lug D^{19} , which has a perforation D^{68} therethrough, through which passes the reduced portion T^{10} of the shank and which is clamped therein in the manner shown in Fig. 61 and which will be presently referred to. The take-up arm T^7 has a slight angular bend at the point where it joins the link T^4 and has also at this point a grooved thread-roller T^{13} and at its outer end a similar grooved thread-roller T^{14} , pivoted, respectively, upon the pivot-screws T^6 and T^{15} , Figs. 2, 4, and 5. It will thus be seen that the cam T is adapted to give the take-up arm T^7 a swinging movement upwardly through an arc somewhat greater than ninety degrees.

With the take-up arm co-operates an auxiliary arm T^{16} , which takes the place of a bracket-arm formerly projecting horizontally from the base-plate D^1 ; but, as herein shown, the arm is of U or J shape, having the shorter arm pivoted upon the bolt T^8 , or rather upon a short sleeve T^{17} , loosely mounted on the shank portion T^{10} of the bolt, which sleeve is adapted to be clamped in position with the other parts and is therefore made slightly longer than the hub T^{18} of the auxiliary arm, Fig. 61, in order to enable the arm to have a free pivotal motion thereon. The auxiliary arm T^{16} passes first downwardly and beneath the take-up arm T^7 , as shown in Figs. 3, 4, and 5, and thence passes upwardly between the two thread-rolls T^{13} and T^{14} and carries at the upper end thereof a grooved thread-roll T^{19} , which is mounted on the pivot-screw T^{20} and has an arched shield T^{21} , Figs. 2, 3, and 5, through the eye of which and over the thread-roll the machine-thread (shown at 81

in Figs. 3 and 5) is adapted to be passed. The auxiliary arm T^{16} is further provided near its base with a compression-spring T^{22} , which is supported in shallow apertures bored 5 in the opposing faces of the auxiliary arm on the frame, as shown in Fig. 58, and which resiliently supports the auxiliary arm in its raised position, so as to hold the thread-roll T^{19} in opposition to the downward motion of 10 the thread-rolls T^{13} and T^{14} . Furthermore, the hub T^{18} of the auxiliary arm has a backwardly-extending tongue T^{23} , (best shown in Fig. 58,) which tongue is adapted to rest normally upon the flat surface of the base-plate 15 D^6 , but to be raised slightly when the auxiliary arm is depressed by the tension of the thread on the roller T^{19} . The amplitude of movement of the auxiliary arm in this instance is accurately adjustable by a set-screw 20 T^{24} , which is seated in a threaded socket in the end of the tongue T^{23} .

At the left of the auxiliary arm T^{16} and upon the reduced portion T^{10} of the bolt T^8 is loosely mounted a drum T^{25} , which is held in 25 position by a sleeve T^{26} , interposed between the drum T^{25} and the shank T^{10} , and has a collar T^{27} at the outer end thereof which cooperates with a suitable groove formed in the drum T^{25} and prevents it from shifting laterally thereon. The sleeve T^{26} is adapted to 30 be clamped fast to the bolt in stationary position by means of the tightening-nut T^{28} and is therefore made slightly longer than the drum T^{25} in order to permit the free play 35 of the latter thereon, as shown in Fig. 61. At its end adjacent to the auxiliary arm T^{16} the drum T^{25} carries a sheave T^{29} , having a deep V-shaped groove T^{30} therein, which is adapted to receive and securely hold the 40 thread, which is wound in a single turn around the sheave T^{29} and in the groove thereof before passing to the thread-rolls T^{13} , T^{19} , and T^{14} . The object of this drum and sheave is to prevent back motion of the thread and 45 secure it against being drawn backwardly by the motion of the pull-off mechanism, to be hereinafter described, and to this end I provide on the outer or left-hand end of the drum T^{25} a ratchet-wheel T^{31} , with the teeth 50 of which engages a pawl T^{32} , mounted upon a pivot-screw T^{33} , carried by a short forwardly-projecting arm T^{34} , which is mounted upon the end of the shank T^{10} of the bolt T^8 , all as clearly shown in Figs. 3, 4, 57, and 61. 55 The arm T^{34} has at its end a small wire spring T^{35} , secured thereto by a screw T^{36} , which spring is adapted to press against the under side of the pawl and hold it in engagement with the teeth of the ratchet-wheel T^{31} , it being understood that these teeth are pointed in a left-handed direction, whereby to prevent the backward rotation of the drum T^{25} . The bolt T^8 and the sleeves T^{17} and T^{26} thereon, together with the arm T^{34} , are all securely 60 clamped fast in rigid position by means of the nut T^{28} , and thus the arm T^{34} is prevented from being rotated by the reaction of the

ratchet-wheel, while at the same time it may be readily adjusted in angular position.

In order to prevent the thread from being drawn from the wax-pot instead of from the thread-loop of the stitch during the motion of the take-up, it is necessary to provide a lock against the forward motion of the thread at some point thereof, and this is done in the present case in the same manner as in the ordinary type of stitcher by means of a locking-lever V^1 , which is pivoted upon the same bolt 79, carried by the post D^4 , as the awl-lever and has a forwardly-projecting arm 80 carrying at its extremity a trundle-roller V^2 , which rolls upon the hub-cam V of the thread-lock motion, this cam being of the form shown in dotted lines in Figs. 4 and 5. At an intermediate point of the cam-lever is provided a 85 post V^3 , to which is attached a tension-spring V^4 , whose other end is attached to a small post V^5 , projecting from the side of the post D^4 , the function of this spring being to maintain the cam-roller V^2 in engagement with the 90 surface of the cam V . The lever V^1 has a backwardly-extending arm V^6 , which is provided at its extremity with an upright post V^7 , clamped thereto by a screw V^8 , which is adapted to press against the tension-wheel 82, supported on a bracket 83, projecting rearwardly from the pedestal 68. The cam V , as shown, consists of two circular portions V^9 and V^{10} , of different diameters joined by inclines at their ends, and it will be seen that during 100 the time that the cam-roller V^2 rests upon the larger circular portion V^{10} it will support the post V^7 away from the tension-wheel 82 and leave the thread free to be drawn from the latter by the pull-off mechanism; but when 105 the cam-roller V^2 rests upon the smaller circular portion V^9 of the cam it will allow the spring V^4 to draw the post V^7 against the tension-wheel and into the groove 83^a thereof with sufficient friction to securely lock the 110 tension-wheel against movement, this operation taking place during the downward thrust of the take-up motion, as will be seen by the relative positions of the two cams shown in 115 Figs. 4 and 5. The tension-wheel, as shown in Fig. 1, is provided with the usual friction device, such as a friction-disk 84, pressed into contact with the side of the wheel by a spring 85, which rests against a hand-nut 86 and is 120 supported in the end of the bracket 83 and on which the spring 85 is supported.

The feed-motion.—This, as herein described, includes three separate cams and their levers—that is to say, the feed-cam F and its lever F^1 , which causes the reciprocation of the feed-carriage carrying the awl, the presser-foot, and the work-gage at its lower depending end, the presser-foot cam P and its lever P^1 , which at the times of feeding the work 125 forward depresses the presser-foot and raises the same after the feed-motion of the carriage is complete, and the table-locking cam W and its lever W^1 , which causes the work table or

support to be locked in position during the feeding movement in order to support the work during the formation of the stitch and on the forward motion of the carriage. These 5 several parts and the mechanism coacting therewith are exhibited in detail on Sheets 12, 14, 15, and 16 of the drawings, besides being shown in their general position in the machine on Sheets 1 to 6. The feed-carriage, 10 which is the most important of these parts and upon which most of them are mounted, is shown by itself in Fig. 48, being in the form of a horizontal slide-block F², having at its left-hand or inner end a rectangularly-depending limb F³, which is adapted to reciprocate between the two posts D¹² D¹³ of the work-head and on the right-hand side of the space therebetween. The block F² is arranged to slide in the channel D¹⁸, cut for 15 it in the block D¹⁶, forming the upper portion of the post D¹³ of the work-head; but in order to take up wear caused by the continual reciprocating movement of the carriage there is provided at one side of the 20 channel D¹⁸ a wear-plate or shim F⁴, which is adapted to lie between the abutting faces of the channel D¹⁸ and the block F² and to be adjusted to take up the lost motion by means 25 of a pair of set-screws F⁵, which are socketed in screw-threaded apertures D⁶⁹ in the block D¹⁶ and whose inner ends abut against the shim and lie in shallow recesses therein, whereby the shim is prevented from moving 30 longitudinally with the carriage. The carriage is held against rising in its slideway by two overlapping plates F⁶ F⁷, the former of which is secured to the forward side of the planed surface D¹⁷ of the block D¹⁶ by means 35 of a pair of screws and a pair of dowel-pins 40 passing, respectively, through screw-holes D⁷⁰ and pin-holes D⁷¹, while the plate F⁷ forms an extension of the block S¹⁴, Fig. 38, and is secured to the rear face D¹⁷ of the block D¹⁶ by means of screws and dowel-pins seated, 45 respectively, in the holes D⁶⁶ D⁷². The upper surface of the block F² is provided with rectangular grooves F⁸ F⁹, which receive the projecting ends of the plates F⁶ F⁷ and form the upper surface F¹⁰ of the block flush with the 50 upper surface of the plates F⁶ F⁷. The surface F¹⁰ is pierced by oil-holes F¹¹, leading to the lower surface and forming lubricating means, and also with other screw-holes, which receive the ends of bolts and screws to be 55 presently described. The parts mounted in stationary position on the upper surface of the carriage are shown in Fig. 47 and comprise a transverse rectangular guide-plate F¹², which projects transversely to the rear over 60 the side of the carriage and toward the feed-cam F and has a longitudinal rectangular slot F¹³, the piece F being secured to the carriage by means of a pair of screws F¹⁴ and a pair of dowel-pins F¹⁵, extending, respectively, 65 through the holes F¹⁶ and F¹⁷. On the right of this guide-plate is mounted an arc-shaped bar F¹⁸, which is provided with a plate F¹⁹, se-

cured to the end of the carriage by a single screw F²⁰ and dowel-pins F²¹, seated in the apertures F²². This bar F¹⁸ is perforated with 70 a series of equidistant holes F²³, which are adapted to receive pins F²⁴, for the purpose hereinafter named. On the left of the guide-plate F¹² and in the center line of the carriage is pivotally mounted upon a pivot-bolt F⁵⁰, 75 secured in a screw-threaded aperture F⁵¹ in the block F² of the carriage, a stitch-adjusting lever F²⁵, which is in the form of a flat plate, having a longitudinal slot F²⁶ at the point where it passes over the guide-plate F¹² 80 and a handle-knob F²⁷ upon its outer end. The feed-lever, as shown in Fig. 1, is mounted longitudinally over the guide-plate F¹² and is likewise provided with a longitudinal slot F²⁸ therein, and it is pivoted upon an eccentric pivot-pin F²⁹, passing vertically through the plate F⁶ and through an aperture D⁷³, formed in the center of the front face D¹⁷ of the block D¹⁶. The pivot-pin F²⁹ is shown in 85 detail in Fig. 53, being provided with a reduced lower end F³⁰, adapted to be clamped in the aperture D⁷³ by means of a set-screw F³¹, Fig. 41, which is screwed into an aperture D⁷³ in the end of the block D¹⁶. (Shown in dotted lines in Fig. 9.) The upper end F³² 90 of the shank is made eccentric, as shown, in order to adapt the pivot of the feed-lever F¹ to be adjusted forwardly and backwardly to a certain extent, and to this end the head F³³ of the pin F²⁹ is transversely pierced by a hole F³⁴ for the insertion of a bar, and it is also provided with an oil-conduit F³⁵ for the lubrication of the hub F³⁶ of the feed-lever. The stitch-adjusting lever and the feed-lever are joined together by a peculiarly-shaped 105 block F³⁷, (shown in detail in Fig. 54,) this block having flattened sides F³⁸, which operate against the inner sides of the slot F²⁸ of the feed-lever; a cylindrical collar F³⁹, which is received in the slot F²⁶ of the stitch-adjusting lever; a depending stud F⁴⁰, which forms a pivot for a square sliding block F⁴¹, adapted to fit and to reciprocate in the slot F¹³ of the rectangular guide-plate F¹², and a screw-threaded stud F⁴² on the upper end thereof, 110 which is capped by a nut F⁴³, securing the block F³⁷ in position. It will be seen that by the medium of the block F³⁷ and its connections the feed-lever is connected with the carriage, so as to reciprocate the same longitudinally by means of its transverse motion, while the amplitude of motion of the carriage is governed by the position of the stitch-adjusting lever F²⁵, which reciprocates the block F³⁷ toward and from the pivot-pin 115 F²⁹ of the cam-lever F¹ and is held in a fixed position by means of the pins F²⁴, as shown in Fig. 1, and a further adjustment is provided by the eccentric shank F³² of the pin F²⁹. The feed-lever has at its rear end a 120 trundle-roll F⁴³, which is mounted to turn on a countersunk shoulder-bolt F⁴⁴, secured to the feed-lever by the nut F⁴⁵, and projects into the groove F of the feed-cam. 125 130

The depending leg F³ of the carriage is formed with a downwardly-slanted oblique front face F⁴⁶, which has a longitudinal recess or slot F⁴⁷ therein, in which is adapted to fit and reciprocate the presser-foot bar P². (Shown in enlarged detail in Fig. 52.) To retain the presser-foot bar in its slot, there is provided a cover-plate P³, which is secured on the face F⁴⁷ by means of screws P⁴. The lower end of the bar P² carries a lug P⁵, to which is secured, by means of screws P⁶, the presser-foot P⁷, which is of the ordinary type, and the upper end of the bar P² has a lug P⁸, with a threaded aperture P⁹, in which is mounted a pivot-screw P¹⁰, having a flat-sided block P¹¹ rotatably mounted thereon, which is engaged by the forked end P¹² of the presser-foot cam-lever P¹, which is pivotally mounted upon a stud P¹³, projecting into an aperture F⁴⁸ in the end of the block F² of the feed-carriage and secured therein by a set-screw P¹⁴, passing through the aperture F⁴⁹. The presser-foot lever P¹, together with the presser-foot, is thus arranged to reciprocate with the feed-carriage and to move back and forth on its cam P, which has a greater width than the roller P¹⁵, carried by the end of the lever, as seen from Fig. 1.

At the inner side of the depending leg F³ on the feed-carriage is shown an oblique shallow recess F⁵², where the block is cut away to enable the latter in its motions to avoid interference with the bearing-boss H²⁵ on the rear of the thread-hook block. (See Fig. 10.) Below the recess F⁵² and near the lower end of the leg F³ is formed a rectangular groove F⁵³, which is destined to receive the work-gage U¹, which is, as shown in Figs. 47 and 50, in the form of a short rectangular plate, having rack-teeth U² formed on its upper surface, and a rectangularly-bent finger U³, which forms the gage and co-operates with the presser-foot P⁷ and the work-table in striking against the edge of the work and regulating the distance between the edge and the seam. The work-gage U¹ has also a longitudinal slot U⁴ formed therein, through which passes the pivot-pin A⁷ of the awl-block, which is mounted in a threaded aperture F⁵⁴ in the leg F³, so that the awl likewise vibrates with the carriage and partakes of the feed-motion thereof.

The work-gage motion, which forms one of the important features of my invention, is shown in general perspective in Fig. 43, Sheet 5, 12, and it differs from all preceding motions in having a stationary adjusting-handle U⁵, which is bent at right angles, as shown at U⁶, and the end is provided with a hub U⁷, connected by a set-screw U⁸ to the adjusting-shaft U⁹, which is pivotally mounted in a stationary block U¹⁰, (shown in detail perspective in Fig. 45,) which is secured to the lower side of the block D¹⁶ of the work-head by screw-bolts or other like fastenings passing through vertical apertures U¹¹. The shaft U⁹ is mounted in a transverse horizontal aperture U¹² in the block U¹⁰, and this aperture

U¹² is connected with the exterior of the block by a cut U¹³, the object of this cut being to divide the block, so as to enable one of the 7c screws securing it to the work-head to be tightened to the requisite extent to produce a certain amount of friction upon the shaft U⁹ to prevent its being accidentally moved, or by the reaction of pressure on the work-gage, and otherwise, except when it is positively moved by the handle U⁵. The shaft U⁹ extends inwardly to a point opposite the end of the block D¹⁶, and upon this end is mounted a gear-segment U¹⁴, which has an 80 aperture U¹⁵, passing over the stud U¹⁶ on the end of the shaft, to which it is keyed by means of pins U¹⁷, seated in notches U¹⁸ in the interior face of the aperture U¹⁵, and is prevented from coming off the shaft by a nut U¹⁹ on 85 the screw-stud U²⁰, these parts being shown in detail in Fig. 44. The gear-segment is arranged to mesh with a gear-pinion U²¹, which is mounted upon a short counter-shaft U²², carried in an aperture F⁵⁵ in the depending leg F³ of the carriage, and the gear-pinion U²¹, as herein shown, is clamped in position on the shaft U²² by clamping-ears U²³ and a screw U²⁴. The other end of the shaft U²² is provided with a pinion U²⁵, which is on the opposite 95 face of the leg F³ of the feed-carriage, and is seated in a circular recess F⁵⁶, so as to be flush with the face of the leg F³, as shown in Fig. 47, this pinion U²⁵ being arranged to engage the rack U², formed on the work-gage U¹. It will be seen that by pulling the handle U⁵ forwardly the work-gage, with its gage-finger U³, is likewise caused to be pushed forwardly to the extent desired, but the shaft U⁹ is clamped firmly enough in the block U¹⁰ to 105 prevent the pressure of the work from reacting upon the gage sufficiently to move it back. The hub U⁷ of the adjusting-handle is provided with a radially-projecting boss U²⁶, from which proceeds the handle-arm U⁶, and which is adapted to coact with a tangential stop-screw U²⁷, mounted in a transverse aperture in a pin U²⁸, which is secured in an aperture D⁷⁴ in the end of the block D¹⁶ of the work-head, and secured therein by a clamping-screw U²⁹. The stop-screw U²⁷ may be adjusted to limit the forward movement of the work-gage to any requisite extent, and it is provided with a lock-nut U³⁰, which clamps it in the position to which it is set. It will 110 be observed that the pinion U²¹ is made with a wider face than the gear-segment U¹⁴, so that while the latter is stationary the former in reciprocating shall always be in full intermeshing engagement with the said gear-segment, thus providing for the adjustment 115 of the work-gage during the operation of the machine, while the adjusting-handle remains stationary.

The pull-off, measuring, and lock-regulating mechanisms.—In former machines of this type the pull-off motion was performed as an adjunctive function of the awl-lever by means of an arm projecting rearwardly from the

5 pivot 79 of the latter, (see Fig. 5,) but owing to the position of the tension-wheel, the pull-off fork had to be located between the latter and the pivot of the awl-lever and very close to the latter, so that it was impossible to give the pull-off sufficient thread for the stitch in the case of thick seams, in which case it happened that the thread would break, owing to insufficient thread being supplied. Moreover, this arrangement, disadvantageous as it was, required the necessity of certain parts projecting from the rear of the machine, where they were liable to become broken and to be in the way. In my present arrangement, 15 however, I have dispensed entirely with the rearwardly-projecting arm of the awl-lever, and have substituted for the projecting pull-off device a pivoted thread-measuring truck Q¹, which is pivotally mounted on the same bolt A⁹, Figs. 5 and 6⁴, as serves to attach the trundle-roll A⁸ to the awl-lever. This thread-measuring truck is shown in detail in Figs. 64 and 66, and consists of a head Q², forming the pivot end of a depending post Q³, which 25 is guided in the longitudinal aperture Q⁴ of a swiveled guide-sleeve Q⁵, which is mounted to turn about a transverse axis formed by a pivot-bolt Q⁶, screwed into the rectangularly-projecting lug Q⁷, the lower end of the sleeve Q⁵ being arranged to play in a slot D⁷⁵ in the base-plate D⁶, which is seated over the cored recess 89 in the pedestal of the machine, thus giving ample freedom for the reciprocative movement of the thread-measuring truck Q¹, 35 while the pivot-bolt Q⁶ is mounted to turn in an aperture D⁷⁶ in the lower rear end of the post D¹² of the work-head. The thread-measuring truck is thus free to reciprocate within the swiveled guide Q⁵, and the post Q³ of the 40 truck has a longitudinal diametrical slot Q⁸, through which is adapted to pass the machine-thread 81, as seen from Fig. 5. The bottom of this slot is preferably not fixed, but is made adjustable by means of a screw 45 Q⁹, which is adjustably mounted in a tubular aperture Q¹⁰, Fig. 66, bored in the end of the post Q³, and the screw Q⁹ has preferably a concavity Q¹¹ at its end, which is rounded off so as to receive the thread without rubbing 50 or cutting the same. The adjusting-screw Q⁹ is not essential to the operation of the machine when the latter is provided with the other thread-measuring devices, to be hereinafter described; but it is intended to regulate the amount of thread pulled from the tension-wheel in conjunction with the measuring-roll Z¹ and the lock-regulating roll R¹, which are located on respectively opposite sides of the thread-measuring truck Q¹ and 55 which coöperate with it in a manner to be presently described. The slot Q⁸ is made elongated, so that the thread passes through the same untouched when the truck is on its downward motion, and for the same reason 60 the truck-guide Q⁵ is also transversely slotted, as shown at Q¹², Figs. 5 and 65, to permit the passage of the thread therethrough,

and when the awl-lever is raised by the rotation of the awl-cam A the adjustable end of the screw Q¹¹ strikes the thread 81 and pulls it off from the tension-wheel, which is at this point released by the thread-locking lever V¹, so as to form a loop therein sufficient for the formation of the next stitch, the thread-loop being caught during this operation by the under sides of the thread-rolls R¹ and Z¹. 75

The measuring-roll Z¹ is, as shown in Fig. 60, a simple concave post affixed to the end of a rectangular projecting lug Z² on the arched rock-arm Z³, which is provided with a hub Z⁴, 80 pivoted upon a threaded pivot-screw Z⁵, secured in the threaded aperture D⁷⁷, bored tangentially in the front of the base-plate D⁶ of the frame and supported at its opposite end in the middle of the base-plate, as shown in Fig. 58. The rock-arm Z³ passes upwardly and downwardly in arched or U form, passing over the machine-thread, and thus being out of the way of the latter, while its free extremity is located close to the inner face of the post D¹³, and this extremity is pivotally connected, as shown at Z⁶, to a link Z⁷, which passes backwardly around the rear side of the post D¹³ and is connected by a pivot-screw Z⁸ to the locking-bar W² of the table. This bar 90 is of the form shown in detail in Fig. 62, having at its front end a pair of upstanding lugs W³ W⁴, which engage between them a depending tooth W⁵, carried by the table-bracket W⁶. (See Fig. 56.) This table-bracket has a forked head W⁷, the two limbs of which embrace the post D¹³ and are pivoted thereto by a pin W⁸, passing through apertures W⁹ and D⁷⁸, formed in the bracket and the post D¹³, respectively. To the forward side 100 of the bracket W⁶ is clamped, by means of bolts W¹⁰, the table or work-support W¹¹, which is adapted to coöperate with the stitch motion and with the presser-foot in holding the work during the stitching operation, and 105 it is provided with a slot W¹² to receive the awl which passes through the same to pierce the work from the under side and to feed the latter along by the motion of the feed-carriage. The table-bracket is furthermore provided with a roller W¹³, pivotally mounted on a screw W¹⁴ at the right side thereof, against which is adapted to abut the shank of the table-lever W¹⁶, which is mounted to turn about a pin W¹⁷, secured in an aperture D⁷⁹ in the 110 side of the post D¹³, and the table-lever W¹⁶ is provided with a downwardly-extending handle W¹⁸ and a stop-lug W¹⁹, which abuts against a pin W²⁰ and limits the forward motion of the table-lever. The lever W¹⁶ has a 115 cam-faced hub W¹⁵, which, as shown, is adapted to abut against the faced end W²¹ of the locking-lever W¹, whereby the backward pressure of the handle W¹⁸ will cause the locking-lever to be turned about its pivot upon the pin W²², which is mounted in the aperture D⁸⁰ in the side of the post D¹³. This locking-lever is provided with a rearwardly-extending tail W²³, which is notched, as shown at W²⁴, 120

- for the attachment of the loop W^{25} of a coiled spring W^{26} , whose other end W^{27} is looped into an eye formed in the end of a tension-screw W^{28} , which passes through a vertical diametrical hole formed in the pin 80 and is adapted to be adjusted to increase or diminish the tension of the spring W^{26} by means of a hand-nut W^{29} on its upper end. The tail W^{23} of the locking-lever carries, furthermore, a cam-roller W^{30} , which is held by the spring in engagement with the surface cam W of the locking-lever, and, as will be seen from Fig. 4, this cam is formed circular for its entire circumference, with the exception of a small portion shown just above and to the right of the cam-roller in Fig. 4, which portion is slightly raised, so as to depress the cam-roller and slightly turn the locking-lever about its pivot, so as to raise a depending foot W^{31} , carried thereby, which under ordinary circumstances is adapted to be held by the spring W^{26} firmly pressed against the face of the locking-bar W^2 .
- The locking-bar is guided in slidable relation upon the faced surface D^{25} by means of a guide-plate W^{32} , which is screwed fast to the base-plate D^6 by screws W^{33} and dowel-pins, (not shown,) passing through apertures D^{31} D^{32} in the base-plate, respectively, and the guide-plate W^{32} is provided with a rectangular notch W^{34} , through which depends the foot W^{31} of the locking-lever. Inasmuch as the foot W^{31} is very close to the pivot W^{22} of the lever, it has an extremely slight motion just sufficient to release the locking-bar and allow it to slide freely or to clamp the same firmly in position, for which the spring W^{26} upon the end of the tail W^{23} is amply sufficient. The lugs W^3 and W^4 on the forward end of the locking-bar embrace the tooth W^5 on the depending end of the table-bracket, and the rear end of the locking-bar has a laterally-projecting post W^{35} , between which and a stationary post W^{36} , carried by the guide-plate W^{32} , is extended a spring W^{37} , so as to keep the locking-bar pressed forwardly and by means of the tooth W^5 to keep the table-bracket and the table pressed upwardly toward the presser-foot P^7 . This motion is limited, however, by a stop-screw W^{38} , passing diametrically through the post W^{35} and provided with a lock-nut W^{39} , as shown in Fig. 55, this stop-screw being adjustable to abut against the rear face of the guide-plate W^{32} , whereby the upward limit of the motion of the table may be adjusted. The post W^{35} is itself clamped in place in an aperture in the rear end of the locking-bar W^2 by means of a set-screw W^{40} .
- It will be seen from Fig. 4 that the positions of the parts are so arranged that when the handle W^{18} of the table-lever W^{16} is pressed backwardly the cam W^{15} will first act to raise the locking-lever against the tension of the spring W^{26} , thus releasing the locking-bar, and that a continuance of the motion will cause the shank of the table-lever to be

brought into contact with the roller W^{13} of the table-bracket, thus pushing the table downwardly, this being done in order to allow of the insertion of work in the machine. When the work is being fed at each revolution of the cam W , the locking-lever will be released and the spring W^{37} will cause the table to be pressed upwardly against the work or allow it to be pushed downwardly to admit a thicker piece of leather and, in accordance with the varying thickness of the seam, will cause the arched rock-arm Z^3 to be oscillated and the measuring-roll Z^1 to be raised or depressed in proportion, so as to allow less or more thread to be drawn off by the thread-measuring truck Q^1 at each upward reciprocation thereof, and this adjustment to the thickness of the seam will take place at every stitch.

The lock-regulating device is formed by a roll R^1 , hereinbefore referred to as located on the rear side of the thread-measuring truck—that is to say, on the opposite side from the roll Z^1 —this thread-roll R^1 being, as herein shown, of the same form as the roll Z^1 —that is to say, in the form of a smooth concave post—it being generally unnecessary to use antifriction-rollers for this purpose. The thread-roll R^1 is mounted at one corner of a triangular plate R^2 , which is pivoted at its lower corner upon a pin R^3 , mounted in an upstanding lug R^4 on the forward end of a backwardly-extending bar R^5 , which is firmly fixed at its rear end to a flat head-block R^6 , secured in a notch D^{38} at the back of the base-plate D^6 and just to the left of the rear post D^4 . The upper end of the block R^6 is pierced to provide a pivot for an adjusting-screw R^7 , having a milled head R^8 and whose forward end is pivoted in an upstanding bearing-lug R^9 , and a head R^{10} is fixed to said end to sustain the longitudinal thrust of the screw R^7 in its bearings, while the milled head R^8 has a flanged collar R^{11} abutting against the face of the head-block R^6 for a similar purpose.

Upon the adjusting-screw R^7 is mounted a sliding nut R^{12} , which has on each side depending lugs R^{13} , which embrace the bar R^5 and enable the nut to slide longitudinally without rotating on the screw. The upper end of the nut R^{12} is provided with a notch R^{14} , in which is received the rear end of a link R^{15} , which is pivoted thereto by a transverse pin R^{16} , while the other end of the link R^{15} is pivoted upon a rivet R^{17} at the rear upper corner of the triangular plate R^2 . It will be observed that by this arrangement the rotation of the milled head R^8 will cause the nut R^{12} to be advanced or retracted on the adjusting-screw R^7 , which turns the plate R^2 and causes the thread-roll R^1 to be raised or lowered relatively to the thread-measuring truck Q^1 . The object of this device is to adjust the exact amount of machine-thread which is drawn off the tension-wheel at each elevation of the thread-measuring truck, and thus to regulate the precise distance of the

lock in the seam from the upper side of the seam, this being a matter of considerable importance in sewing two pieces of leather, especially where the thickness of the seam varies greatly from one job to another.

5 *Operation of the machine.*—The operation is similar in a general way to that of the ordinary shuttle-machine, but yet differs in some important respects, owing to the different construction of the parts embodying my improvements.

In preparing the machine for operation the machine-thread 81 is first drawn from the wax-pot and given a turn around the tension-wheel 82 and is thence passed through to the front of the machine beneath the thread-roll R¹ and through the slot Q⁸ of the thread-measuring truck Q¹, thence beneath the measuring-roll Z¹ to the sheave T²⁹, around which the machine-thread is once passed, and thence around the lower side of the roll T¹³ to the take-up arm T⁷, thence around the upper side of the roll T¹⁹, carried by the auxiliary arm T¹⁶, and through the shield T²¹ thereof, thence around the other roll T¹⁴ of the take-up arm, and thence upwardly, being threaded through the eye of the looper L¹¹ and the slot W¹² of the table W¹¹, when the machine-thread will be found in the position shown in Figs. 3 and 5. The bobbin B¹ is now removed from the case B² by turning the tongue B²¹ of the clip B¹⁸ into the position shown in dotted lines in Fig. 34, when the bobbin will readily slide out, and being provided with a suitable coil of thread B²⁵ the end of the latter is passed through the hole B³⁴, the bobbin replaced on its spindle, and the clip B¹⁸ closed again. After the heater in the pedestal of the machine has been lighted and the machine has become warmed up sufficiently it is now ready for the stitching operation. The work is inserted between the table W¹¹ and the presser-foot P⁷ by depressing the former, which is done by pushing backwardly upon the handle W¹⁸ of the table-lever W¹⁶, whereupon the cam W¹⁵ will first operate to turn the locking-lever W¹ about its pivot W²² and raise the foot W³¹ from the locking-bar W² to release the same, after which the shank of the lever W¹⁶, striking against the roller W¹³, carried by the table-bracket W⁶, will turn the table-bracket and depress the projecting table. When the table-lever is again released, the spring W³⁷ will push the locking-bar W² forward and by the engagement of the latter with the tooth W⁵ of the table-bracket will raise the table W¹¹ until it abuts against the lower face of the work, thus holding it in position, while the locking-lever W¹, being again released, is again brought into position to lock the bar, and hence the table, by means of the spring W²⁶. The machine now being set in motion, the first operation upon the work is that of the awl A⁶, which is oscillated upwardly through the work into the position shown in Fig. 5 by means of the awl-lever A¹, which is depressed by the cam

A, at the same time carrying downwardly the thread-measuring truck Q¹ in position ready to draw off a length of thread 81 from the tension-wheel 82. As the awl rises through the work, making a hole therethrough, the feed-lever F¹ comes into operation to advance the carriage F² toward the left, the presser-foot P⁷ being held downwardly against the upper face of the work and its serrated face engaging the latter, so that in conjunction with the awl the coming work is advanced by the length of a stitch, which length is regulated, as above pointed out, by means of the radial adjustment of the handle F²⁷ upon the bar F¹⁶, the block F³⁷ sliding in the slot of the rectangular guide-plate F¹². When the forward motion of the feed-carriage is completed, the presser-foot is raised by the action of the cam-lever P¹, actuated by the presser-foot cam P, and at the same time the awl A⁶ is retracted from the work, and the carriage then returns to its original position. As the awl is retracted from the hole in the seam the needle N⁵ is brought into operation, being turned downwardly and passed through the hole made by the awl by the action of the needle-lever N¹, which is raised by the cam N, and the needle is accompanied in this operation up to a certain point by the needle-guide G², which is advanced through the action of its cam G as far as possible down the stem of the needle. When the needle has passed through the awl-hole, the looper L¹¹ and thread-finger M² are conjunctively brought into operation, the latter seizing the thread 81 and drawing it backwardly by the action of the thread-finger cam and lever, while the looper takes a turn around the needle-head and causes a loop of thread to engage in the barb thereof. The needle then is caused by the rotation of the needle-cam N to pass back up through the work again, carrying with it the engaged thread-loop of the machine-thread 81, and owing to the raised steps M²² M²³ of the cam M, Fig. 6, the thread-finger is gradually let out, so as to release a certain amount of the engaged thread. As the needle now reaches a limit of its upward movement the oscillating thread-hook H³⁶ is given a quick forward oscillation by its cam H and lever H¹, acting through the medium of the gear-segment H²² and the pinion H²³; but it is accompanied in this movement by a slight lateral and forward oscillation of the spreading-finger S⁵, which is caused to assume a position directly under the thread-hook in readiness to enter the thread-loop when drawn backwardly by the latter. The point H⁴⁰ of the thread-hook H³⁶, Fig. 13, after entering this loop passes to a certain distance beyond it until the bight of the loop slips over the nose H⁴² of the thread-hook and is engaged in the bight H⁴³ thereof. (See Fig. 14.) During the forward motion of the thread-hook and its engagement with the loop of machine-thread the needle is caused to be engaged between the faces of the re-

cess or groove H^{56} in the rear side of the point of the hook, so that the loop being drawn over the point of the hook is gradually raised and delivered from the needle, as shown in Fig. 21. The thread-hook now starts on its retreating movement, drawing out the thread-loop on its way, as shown in Figs. 20 and 15. During this operation a second movement of the spreading-finger takes place, it being given a backward oscillation, so as to strike the rear lap of the thread-loop and raise it clear of the point H^{40} thereof to prevent the thread from snapping thereover or being cut thereon, and after thus lifting the thread over the point of the hook the spreading-finger is moved forwardly again until the loop is released and carried off the end of the spreading-finger, after which the latter is again returned to the back of the raceway. As the thread-hook continues its retreating movement it assumes successively the positions shown in Figs. 20, 15, and 16, in the last of which it is represented as having reached the limit of its backward movement and as having drawn the thread-loop completely around the bobbin-case B^2 , which is easily accomplished by the loose play of the latter within its box. The drawing out of the thread-loop and the oscillation of the thread-hook is very quickly performed, and as the thread-loop is drawn out the take-up lever T^1 is given a quick swing by its cam T , (see Fig. 5,) thus swinging the take-up arm T^7 upwardly and releasing enough thread to permit of the drawing out of the thread-loop by the thread-hook around the bobbin; but as soon as the thread-hook reaches the position shown in Fig. 16 the take-up lever is swung downwardly again by the take-up cam and the take-up arm T^7 is likewise swung downwardly, drawing the loop down on the left-hand side of the bobbin-case, as shown in Figs. 16 and 17, and finally pulling the thread-loop taut and drawing the bobbin-thread through the seam an appropriate distance to properly position the lock therein, which distance is regulated by the position of the lock-regulating roll R^1 . At the end of the downward swing of the take-up arm T^7 or at any point of its downward movement to prevent any sudden jar upon the thread and breaking of the same the yieldable mounting of the auxiliary arm T^{16} , effectuated by the spring T^{22} , enables the said auxiliary arm to give to a slight extent, whereby the thread is prevented from becoming broken. When the take-up arm T^7 moves downwardly to take up the thread-loop, at the same moment the thread-lock lever V^1 is brought into action by its cam V and pressing in the groove 83^a of the tension-wheel 82 prevents the latter from rotating in order to keep the take-up arm from drawing new thread from the wax-pot. During the take-up operation the tail-shield H^{39} of the thread-hook is caused to project over the needle and guard the same, as shown in Figs. 16, 17, and 22, so as to prevent the thread-loop from be-

coming entangled with the barb of the needle, and the bobbin-thread is kept taut by the pressure of the spider-spring B^{26} against the end of the friction-sleeve B^{16} . Meanwhile as the awl-lever A^1 moves upwardly in removing the awl from its awl-hole the thread-measuring truck Q^1 is carried up with it, and the bottom of the slot Q^8 , formed by the adjustable screw Q^9 , strikes against the machine-thread and coöperates with the rolls $R^1 Z^1$ to draw a loop of thread upwardly sufficient for the following stitch, this additional thread being taken entirely from the tension-wheel 82, which is during this time released by the thread-lock lever V^1 , because the pawl T^{32} , engaging with the teeth of the ratchet-wheel T^{31} on the drum T^{25} , forming a part of the sheave T^{29} , prevents the backward rotation of the sheave, and hence prevents the drawing of thread from the front of the machine. At each revolution of the main shaft—that is to say, just before each stitch is taken—the raised portion of the cam W , striking against the roller W^{30} of the locking-lever W^1 , turns it about its axis to release the locking-bar W^2 , and at this point the latter, under the influence of the spring W^{37} , coöperating with the table W^{11} to press the latter against the lower face of the seam, will be moved back and forth, according to the thickness of the seam, and will consequently move the measuring-roll Z^1 down or up to the necessary extent, thus causing a greater or lesser loop of thread to be drawn off by the thread-measuring truck, according to the greater or less thickness of the seam. After the thread-loop has been drawn up taut by the take-up motion the feed-carriage, having been returned to its original position, is prepared to advance the work again, the awl having meanwhile been raised through the seam to make another perforation, and the presser-foot being again depressed when the carriage bearing the awl and presser-foot is again advanced, and the operation proceeds as before. It will be observed that at any time during the operation of the work the stationary handle U^5 may be adjusted to regulate the distance of the seam from the edge of the leather, according as may be desired, without in any way interfering with the operation of the seam, and, in fact, the gage may be continuously adjusted as the work proceeds, so as to continuously vary the distance of the seam from the edge of the work, an operation which has not been practically possible in any former type of machine. The position of the lock—that is to say, its distance from the upper face of the seam—may also be regulated by simply turning the milled head R^3 , as will be seen, this causing a definite alteration in the length of thread which is drawn off by the thread-measuring truck Q^1 . It is, however, to be observed that the lock-regulating device, comprising the adjustable roll R^1 , and the adjusting-screw Q^9 , carried by the thread-measuring truck Q^1 , are to a certain extent comple-

mentary, performing approximately the same function in regulating the length of loop drawn off, but in different ways. As the milled head R⁸ presents a more convenient means of adjusting the position of the lock than the screw Q⁹, which is mounted internally within the mechanism in ordinary machines, the screw Q⁹ may be entirely dispensed with; but it is useful in certain cases where an extraordinary degree of adjustment is required.

From the above description the many advantages and points of superiority of my new machine over the machine formerly in use will be apparent to those skilled in the art and will not, it is thought, need further enumeration.

While I have shown in the accompanying drawings the preferred form of my invention, it will be understood that I do not limit myself to the precise form shown, nor do I limit myself to the employment in the machine of all of the improvements, for the different features may be used separately in many cases with advantage, and many of the details may be changed in form or position without affecting the operativeness or utility of my invention, and I therefore reserve the right to make such modifications as are within the ability of the skilled mechanic and those skilled in the art generally.

Having now particularly described and ascertained the nature of my said invention and in what manner the same is to be performed, I declare that what I claim is—

1. In a shoe and leather sewing machine, the combination of a stitch-forming element having a point adapted to enter and seize a thread-loop, a spreading-finger mounted adjacent to said element and parallel thereto and between the same and the work, and means for vibrating said spreading-finger from side to side while the stitch-forming element is picking up the loop, whereby to spread the loop thereover and cause it to pass easily over the point of said stitch-forming element.

2. In a shoe and leather sewing machine, an arcuate stitch-forming element adapted to move in a circular path around its geometric center and having a point adapted to enter and draw out a thread-loop, a spreading-finger mounted in the plane of movement of said stitch-forming element and between the same and the work and projecting close to the thread-loop when picked up by the point of said stitch-forming element, and means for vibrating said spreading-finger from side to side transversely whereby to facilitate the passage of the loop over the neck of said stitch-forming element.

3. In a shoe and leather sewing machine of the lock-stitch type, the combination of an oscillatory arcuate thread-hook having a forwardly-directed point adapted to enter an incipient thread-loop and a recurved nose adapted to draw out the same, a spreading-finger mounted in the plane of said thread-hook and

between the same and the work and projecting close to the recipient thread-loop, and means for giving said spreading-finger transverse vibratory movement during the picking up of the thread-loop by said hook.

4. In a shoe and leather sewing machine of the lock-stitch type, the combination of a curved needle, means for advancing said needle through the work, means for engaging the machine-thread with the barb of said needle, means for retracting said needle for drawing the loop of thread through the work, an arcuate thread-hook adapted to oscillate in a circular raceway above the work, said thread-hook having a forwardly-directed point and a recurved nose, a stationary bobbin adapted to carry thread mounted in the center of said raceway, means for advancing said thread-hook through the loop of thread until said loop is caught over the bight of said nose, means for retracting said thread-hook to draw the loop over the bobbin, and a spreading-finger arranged to project down and into the incipient thread-loop and to be oscillated forward and backward to spread said loop and to lift the same off the point of said hook on the retreating movement of the thread-hook.

5. In a shoe and leather sewing machine of the lock-stitch type, the combination of a curved needle, means for advancing said needle through the work, means for engaging the machine-thread with the barb of said needle, means for retracting said needle for drawing the loop of thread through the work, an arcuate thread-hook adapted to oscillate in a circular raceway above the work, said thread-hook having a forwardly-directed point and a recurved nose, a stationary bobbin adapted to carry thread mounted in the center of said raceway, means for advancing said thread-hook through the loop of thread until said loop is caught over the bight of said nose, means for retracting said thread-hook to draw the loop over the bobbin, a spreading-finger arranged to project down and into the incipient thread-loop and to be oscillated forward and backward to spread said loop, and means for drawing up the loop of thread after it has been passed over the said stationary bobbin.

6. In a shoe and leather sewing machine of the lock-stitch type, the combination of a work-support, a barbed needle adapted to be inserted through the work from the upper side thereof, means for advancing the needle through the work, means for engaging a loop of thread with the barb of said needle, means for retracting said needle from the work to draw up the thread-loop, a stationary bobbin carrying thread adapted to be interlocked with said thread-loop, an arcuate thread-hook adapted to be oscillated in a raceway surrounding said bobbin, a depending arcuate spreading-finger projecting forwardly toward the incipient thread-loop, a rock-shaft on which said thread-finger is mounted, a rock-arm on the end of said rock-shaft, a cam carried by the main shaft of the machine, a cam-

- lever engaging said cam and having an angular arm, and a link connecting said angular arm and rock-arm, whereby said cam is adapted to oscillate said spreading-finger.
7. In a shoe and leather sewing machine of the lock-stitch type, the combination of a work-support, a barbed needle adapted to be inserted through the work from the upper side thereof, means for advancing the needle through the work, means for engaging a loop of thread with the barb of said needle, means for retracting said needle from the work to draw up the thread-loop, a stationary bobbin carrying thread adapted to be interlocked with said thread-loop, an arcuate thread-hook adapted to be oscillated in a raceway surrounding said bobbin, a depending arcuate spreading-finger projecting forwardly toward the incipient thread-loop, a rock-shaft on which said thread-finger is mounted, a rock-arm on the end of said rock-shaft, a cam carried by the main shaft of the machine, a cam-lever engaging said cam and having an angular arm, and a link connecting said angular arm and rock-arm, whereby said cam is adapted to oscillate said spreading-finger, said cam being so formed as to give to said spreading-finger a triple oscillation during the advance and retreat of said thread-hook, namely, first, a backward oscillation to spread the thread-loop, second a forward oscillation to assist in laying said loop in the bight of the hook, and third a backward oscillation to lift the thread-loop off the point of the hook.
8. In a shoe and leather sewing machine of the lock-stitch type, in combination with stitch-forming mechanism comprising an oscillatory thread-hook and a stationary bobbin, an arcuate spreading-finger adapted to project downwardly and centrally to the incipient thread-loop, a horizontal rock-shaft extending to the side of the machine on which said spreading-finger is mounted, a rock-arm mounted on the outer end of said rock-shaft and extending upwardly therefrom, a spreading-finger cam mounted on the right-hand end of the machine-shaft and having an upwardly-extending arm extending over the feed-carriage, and a link passing likewise over the carriage and connecting said upwardly-extending arm with said rock-arm.
9. In a shoe and leather sewing machine of the lock-stitch type, the combination of an awl-lever, a cam coöperating with said lever to reciprocate the same, and a pull-off mechanism mounted on the main portion of said awl-lever at an intermediate point thereof.
10. In a shoe and leather sewing machine of the lock-stitch type, the combination of an awl-lever, a cam adapted to reciprocate said lever, and a thread-measuring truck pivotally mounted at an intermediate point of said lever.
11. In a shoe and leather sewing machine of the lock-stitch type, the combination of an awl-lever pivoted at the rear of the machine and carrying a gear-segment at its forward end, a cam-roller carried at an intermediate point of said lever, a cam engaging said roller to reciprocate said lever, and a pull-off device mounted on the same axis with said cam-roller.
12. In a shoe and leather sewing machine of the lock-stitch type, the combination of a cam-lever pivoted at its rear end and having means for engaging the awl-block at its front end, means for reciprocating said lever, and a thread-measuring truck at an intermediate point of said lever, said thread-measuring truck consisting of a depending bar having a longitudinal slot therethrough adapted to receive the thread.
13. In a shoe and leather sewing machine of the lock-stitch type, the combination of a cam-lever pivoted at its rear end and having means for engaging the awl-block at its front end, means for reciprocating said lever, a thread-measuring truck at an intermediate point of said lever, said thread-measuring truck consisting of a depending bar having a longitudinal slot therethrough adapted to receive the thread, and an adjustable screw fitting in a longitudinal bore in said truck and adapted to regulate the bottom of said longitudinal slot.
14. In a lock-stitch shoe and leather sewing machine, the combination of a cam-lever pivoted at its rear end, a thread-measuring truck pivoted at an intermediate point of said lever, and means for guiding the lower end of said truck.
15. In a lock-stitch shoe and leather sewing machine, the combination of a cam-lever pivoted at its rear end, a thread-measuring truck pivoted at an intermediate point of said lever, and a swiveled guide-piece embracing the lower end of said truck and adapted to guide the same.
16. In a lock-stitch shoe and leather sewing machine, the combination of a cam-lever, means for reciprocating said lever, a thread-measuring truck carried by said lever and reciprocated therewith, said truck having a longitudinal slot therein, means for adjusting the position of the lower end of said slot, and a pair of thread-rolls located on opposite sides of said truck and adapted to hold the thread while the said truck draws a loop therefrom.
17. In a lock-stitch shoe and leather sewing machine, the combination of a cam-lever, means for reciprocating said lever, a thread-measuring truck carried by said lever and adapted to catch and draw off a loop of thread, and a pair of adjustable thread-rolls located on respectively opposite sides of said truck and coöperating therewith to form said loop.
18. In a lock-stitch shoe and leather sewing machine, the combination of a thread-measuring truck, means for reciprocating the same, and a pair of thread-rolls located on respectively opposite sides of said truck and coöperating therewith, one of said thread-rolls being automatically adjustable to the thickness of the seam and the other of said thread-

rolls being manually adjustable to regulate the position of the lock.

19. In a lock-stitch shoe and leather sewing machine, the combination of a cam-lever, means for reciprocating the same, a thread-measuring truck pivotally mounted at an intermediate point of said lever, means for guiding the lower end of said truck, means carried by said truck for engaging and drawing off a loop of machine-thread, and a pair of thread-rolls coöperating with said thread-measuring truck and located on respectively opposite sides thereof, one of said rolls being adjustably connected with the table, where 15 by the automatic movement of the latter is communicated to said roll to adapt the length of the pulled-off thread to the thickness of the seam, and the other of said rolls being manually adjustable to regulate the position 20 of the lock.

20. In a lock-stitch shoe and leather sewing machine, the combination of a cam, an awl-lever pivoted at its rear end and adapted to be reciprocated by said cam, a gear-segment carried by the forward end of said lever, an awl-block having a gear-segment intermeshing with said first-mentioned gear-segment, means for forming a lock-stitch, means for taking up the thread of said lock-stitch, a thread-measuring truck pivotally mounted at an intermediate point of said cam-lever and having a longitudinal slot therein, a tubular swiveled guide-piece adapted to embrace and guide the lower end of said truck, a measuring-roll at one side of said thread-truck operatively connected to the table of the machine so as to regulate the length of the loop drawn off by the thread-measuring truck according to the thickness of the 40 seam, and a stationary roll mounted on the opposite side of said thread-measuring truck.

21. In a lock-stitch shoe and leather sewing machine, the combination of a cam, an awl-lever pivoted at its rear end and adapted to be reciprocated by said cam, a gear-segment carried by the forward end of said lever, an awl-block having a gear-segment intermeshing with said first-mentioned gear-segment, means for forming a lock-stitch, means 45 for taking up the thread of said lock-stitch, a thread-measuring truck pivotally mounted at an intermediate point of said cam-lever and having a longitudinal slot therein, a tubular swiveled guide-piece adapted to embrace and guide the lower end of said truck, a measuring-roll at one side of said thread-truck operatively connected to the table of the machine so as to regulate the length of the loop drawn off by the pull-off mechanism 50 according to the thickness of the seam, and a stationary roll mounted on the opposite side of said thread-measuring truck, said stationary roll being manually adjustable in height to regulate the absolute length of thread 55 drawn off for each stitch.

22. In a lock-stitch shoe and leather sew-

ing machine, the combination of an awl-lever pivotally mounted at its rear end, means for reciprocating said lever, an awl-block engaged by said lever and reciprocated thereby, means 70 for forming a lock-stitch, a thread-measuring truck mounted at an intermediate point of said lever and having a longitudinal slot therethrough, means for guiding the lower end of said truck, and an antiback-motion device 75 mounted at the front of the machine, comprising a grooved thread-sheave, a ratchet-wheel formed integrally therewith, and a pawl engaging said ratchet-wheel to prevent the back motion thereof during the action of said 80 thread-measuring truck.

23. In a lock-stitch shoe and leather sewing machine, the combination of an awl-lever pivotally mounted at its rear end, means for reciprocating said lever, an awl-block engaged 85 by said lever and reciprocated thereby, means for forming a lock-stitch, a thread-measuring truck mounted at an intermediate point of said lever and having a longitudinal slot therethrough, means for guiding the lower 90 end of said truck, a horizontal pivot-pin mounted in the frame of the machine, a take-up arm pivotally mounted thereon, an auxiliary take-up arm coacting with said first-mentioned take-up arm and likewise mounted 95 on said pin, a drum having a grooved thread-sheave and a ratchet-wheel likewise rotatably mounted on said pin, a pawl-bar also mounted on said pin and clamped thereto, and a pawl carried by said pawl-bar and resiliently pressed against the teeth of said ratchet-wheel to prevent the back motion 100 thereof during the upward movement of said thread-measuring truck.

24. In a lock-stitch shoe and leather sewing machine, the combination of an awl-lever pivotally mounted at its rear end, means for reciprocating said lever, an awl-block engaged by said lever and reciprocated thereby, means 105 for forming a lock-stitch, a thread-measuring truck mounted at an intermediate point of said lever and having a longitudinal slot therethrough, means for guiding the lower end of said truck, a horizontal pivot-pin mounted in the frame of the machine, a take-up arm pivotally mounted thereon, an auxiliary take-up arm coacting with said first-mentioned take-up arm and likewise mounted 110 on said pin, a drum having a grooved thread-sheave and a ratchet-wheel likewise 115 rotatably mounted on said pin, a pawl-bar also mounted on said pin and clamped thereto, a pawl carried by said pawl-bar and resiliently pressed against the teeth of said ratchet-wheel to prevent the back motion 120 thereof during the upward movement of said thread-measuring truck, and a pair of thread-rolls 125 on opposite sides of said thread-measuring truck and coöperating therewith, one of said rolls being connected with the work-table and automatically adjustable up and 130 down therewith according to the thickness

of the seam, and the other of said thread-rolls being manually adjustable to regulate the position of the lock.

25. In a shoe and leather sewing machine, 5 the combination of a pivoted work-table, a locking-bar engaged to be reciprocated therewith, a link connected with the rear end of said locking-bar, an arched rock-arm having its free end connected with said link and its 10 other end carried below said free end and pivoted in the frame of the machine, a thread-roll carried by said arched arm, and pull-off mechanism coöperating with said thread-roll.

26. In a lock-stitch shoe and leather sewing machine, 15 the combination of an arched rock-arm having one arm of the arch longer than the other and the longer arm pivoted in the frame of the machine, a thread-roll projecting between said two arms, whereby the thread 20 is enabled to pass under the arch, pull-off mechanism coöperating with said thread-roll, a movable work-table, and means connecting said work-table with said shorter arm of the arch, whereby to raise and lower said thread- 25 roll.

27. In a lock-stitch shoe-sewing machine, 30 the combination of a frame having a rising post forming a work-head at the front end thereof, a table-bracket pivoted to said post and adapted to oscillate on the right side thereof, a work-table supported by said table-bracket, a reciprocating locking-bar engaged with the lower end of said table-bracket and 35 slidably mounted on the right side of the base of said post and projecting at the back thereof, a link connected with the rear end of said locking-bar and lying at the left of said post, an arch-shaped rock-arm adapted to overlie the machine-thread and connected at its free 40 end to the front end of said link, the longer branch of said rock-arm being pivotally mounted in the frame of the machine, a measuring-roll carried by said rock-arm and projecting between the two branches thereof, and 45 pull-off mechanism coöperating with said measuring-roll.

28. In a shoe and leather sewing machine, 50 a lock-regulating device comprising a movable thread-roll, means operable from the rear of the machine for raising and lowering said thread-roll, and a thread-truck reciprocating across the path of the thread adjacent to said roll.

29. In a shoe and leather sewing machine, 55 the combination of a thread-roll movable up and down, a transversely-moving thread-truck coöperating therewith, a horizontally-movable device connected with said thread-roll, and means operable from the rear of the 60 machine for reciprocating said horizontally-movable device to raise or lower said thread-roll.

30. In a shoe and leather sewing machine, 65 a lock-regulating device comprising a thread-roll adjustable up and down, a transversely-moving thread-truck coöperating therewith, a rotatable milled head, and means connect-

ing said head with said thread-roll whereby the latter is adjusted by turning said head.

31. In a lock-stitch shoe and leather sewing machine, 70 a lock-regulating device comprising a pivoted plate, a thread-roll mounted thereon to be raised or lowered with the oscillation of said plate, a transversely-moving thread-truck coöperating therewith, a screw, 75 means for manually turning said screw, a nut mounted upon said screw to be reciprocated thereby, and a link connecting said nut with said plate whereby the turning of said screw raises or lowers said thread-roll. 80

32. In a lock-stitch shoe and leather sewing machine, in combination with a transversely-moving thread-truck, a lock-regulating device coöperating with said truck and comprising a stationary bar having a head secured to the frame of the machine, an adjusting-screw rotatably mounted in said head and projecting from the rear of said machine and having a milled head thereon, a nut mounted on said screw to be reciprocated thereby and 90 having side lugs engaging said bar to be guided by the latter, a link pivotally connected to said nut, a triangular plate pivotally mounted on the forward end of said bar, and a thread-roll carried at the forward corner of said triangular plate, said link being connected to the opposite corner of said triangular plate whereby the longitudinal movement of said nut causes said thread-roll to be raised and lowered, substantially as described. 100

33. In a lock-stitch shoe and leather sewing machine, the combination of an awl-lever, a cam adapted to reciprocate the same, a pull-off device carried by an intermediate point of said lever and located directly under the 105 main shaft of the machine, a lock-regulating thread-roll coacting with said pull-off device and located at the rear side thereof, a pivoted triangular plate on which said thread-roll is mounted, a bar extending to the rear of the 110 machine and carrying at its forward end said triangular plate, a screw mounted to rotate on an axis parallel to said bar and having a milled head projecting from the rear side of the machine, a nut mounted on said screw 115 and having guide connections with said bar, and a link connecting said nut with said triangular plate to oscillate the same, substantially as described.

34. In a shoe-sewing machine of the lock-stitch type, the combination of an arcuate hooked needle located above the work and adapted to draw a thread-loop therethrough to the upper side thereof, an arcuate thread-hook adapted to take the thread-loop from 125 the needle and carry it over the bobbin, a stationary bobbin-case having a flat closed back and a double-conical-elbowed periphery mounted within and in the plane of said thread-hook, said thread-hook and bobbin-case being in a slightly-inclined plane above and to the rear of the work, a bobbin carried within said bobbin-case, a stationary bracket 130 in front of said bobbin-case and adapted to

support the same and having a slight recess in the lower part of its inner periphery, and a depending lip projecting from the lower side of said bobbin-case at the front thereof and adapted to project into said recess in the bobbin-bracket whereby to permit the thread after passing over said bobbin-case to pass easily out from between it and its bracket at the lowermost contact-point between the bobbin-case and bracket.

35. In a sewing-machine, the combination of a bobbin-case having a doubled-elbowed conical periphery and a smooth exterior without projection thereon, said bobbin-case having a central circular aperture in the front side thereof, a post mounted on the back of said bobbin-case in the center thereof, a bobbin movably mounted on said post and having the front head thereof fitting in the aperture of said bobbin-case and inclosed thereby and forming a smooth continuation of the walls of said bobbin-case, the front head of said bobbin-case having a central annular recess, and a clip on the front end of said post adapted to secure said bobbin in position thereon, said clip being inclosed by said recess so as to leave no point or projection beyond the external surface of the bobbin whereon thread may catch.

30. 36. In a sewing-machine, a bobbin-case having a screw-threaded boss at the center of the back thereof, a post having a shouldered head and a screw-threaded stud adapted to be mounted in said boss, a sleeve having a longitudinal feather rotatably mounted on the reduced portion of said post and of substantially the same or greater external diameter than the head of said post, a spider-spring mounted on said post and pressing 40 against the back of said bobbin-case and the rear end of said sleeve, a pivoted clip mounted on a transverse pintle in a slot in the head of said post, said clip having a squared head and an outwardly-extended tongue, a reciprocating block mounted in a longitudinal bore in said post back of said clip and adapted to press thereagainst and a coiled compression-spring mounted in said bore behind said block, in combination with a bobbin having 45 a grooved hub adapted to coact with said sleeve and to be fitted in operative relation thereto, and an annular recess in the front head thereof adapted to receive the tongue of said clip.

50. 37. In a sewing-machine, a bobbin-case having a screw-threaded boss at the center of the back thereof, a post having a shouldered head and a screw-threaded stud adapted to be mounted in said boss, a sleeve having a longitudinal feather rotatably mounted on the reduced portion of said post and of substantially the same or greater external diameter than the head of said post, a spider-spring mounted on said post and pressing against 55 the back of said bobbin-case and the rear end of said sleeve, a pivoted clip mounted on a transverse pintle in a slot in the head of said

post, said clip having a squared head and an outwardly-extending tongue, a reciprocating block mounted in a longitudinal bore in said post back of said clip and adapted to press thereagainst, and a coiled compression-spring mounted in said bore behind said block, in combination with a bobbin having a grooved hub adapted to coact with said sleeve and to be fitted in operative relation thereto and an annular recess in the front head thereof adapted to receive the tongue of said clip, and a depending lip formed on the lower side of said bobbin-case, said lip being adapted to be engaged loosely in a recess of the bobbin-box to prevent rotation of said bobbin-case, substantially as described.

38. In a shoe and leather sewing machine of the lock-stitch type, the combination of an arcuate stitch-forming element adapted to move in a circular path about a geometric center and to carry a loop over the bobbin, a bobbin-case loosely mounted concentrically with and in the plane of the said stitch-forming element, said bobbin-case having a circular aperture in its front side, a post mounted centrally in said bobbin-case, a bobbin removably mounted on said post and having a head adapted to close the aperture in said bobbin-case and to be inclosed by the margin of said aperture, and an annular bobbin-bracket adapted to support said bobbin at points around its periphery and having an aperture in the center thereof through which 100 said bobbin is adapted to be removed without disturbing said bracket or bobbin-case.

39. In a shoe and leather sewing machine of the lock-stitch type, the combination of an arcuate stitch-forming element adapted to move in a circular path about a geometric center and to carry a loop over the bobbin, a bobbin-case loosely mounted concentrically with and in the plane of the said stitch-forming element, said bobbin-case having a circular aperture in its front side, a post mounted centrally in said bobbin-case, a bobbin removably mounted on said post and having a head adapted to close the aperture in said bobbin-case and to be inclosed by the margin 110 of said aperture, an annular bobbin-bracket adapted to support said bobbin at points around its periphery and having an aperture in the center thereof through which said bobbin is adapted to be removed without disturbing said bracket, said bobbin having a recess formed in the center of the front head thereof, and a clip mounted on the end of said post and adapted to be inclosed by said recess when the bobbin is mounted in position, substantially as described.

40. In a shoe and leather sewing machine of the lock-stitch type, the combination of a stationary block having a circular recess constituting a raceway and a bobbin-box, an arcuate thread-hook mounted to oscillate around the exterior portion of said recess, a centrally-mounted bobbin-case, a bracket secured to the face of said block and adapted to loosely

secure the bobbin-case, and means loosely engaging the bobbin-case with the bracket, whereby to prevent the former from rotating while permitting a loop of thread to be drawn 5 around the same by said hook, substantially as described.

41. In a shoe and leather sewing machine of the lock-stitch type, the combination of a stationary block having a shallow cylindrical recess therein, an arcuate thread-hook mounted upon a shaft having bearings at the rear of said block, means for oscillating said shaft and hook, a bobbin-case loosely mounted in the center of said recess in said block, a bobbin-bracket adapted to loosely retain said bobbin-case in position, and means for adjusting said bobbin-bracket toward or from said block to adjust the amount of play of the bobbin-case.

42. In a shoe and leather sewing machine of the lock-stitch type, the combination of a stationary block having a shallow cylindrical recess therein, an arcuate thread-hook mounted upon a shaft having bearings at the rear 25 of said block, means for oscillating said shaft and hook, a bobbin-case loosely mounted in the center of said recess in said block, a bobbin-bracket adapted to loosely retain said bobbin-case in position, means for adjusting 30 said bobbin-bracket toward or from said block to adjust the amount of play of the bobbin-case, means engaging the bobbin-case with the bobbin-bracket for preventing the rotation of the former while permitting a loop of 35 thread to be turned around the same, and a back plate arranged to shield the bobbin-case and the thread-loop from the oscillating parts.

43. In a shoe and leather sewing machine of the lock-stitch type, the combination of a stationary block having a shallow cylindrical recess therein, an arcuate thread-hook mounted upon a shaft having bearings at the rear of said block, means for oscillating said shaft and hook, a bobbin-case loosely mounted in 45 the center of said recess in said block, a bobbin-bracket adapted to loosely retain said bobbin-case in position, means for adjusting 50 said bobbin-bracket toward or from said block to adjust the amount of play of the bobbin-case, said bobbin-bracket having a central aperture, and a bobbin rotatably mounted in said bobbin-case and adapted to be withdrawn through the front side of said case and through 55 said aperture in the bobbin-bracket.

44. In a shoe and leather sewing machine of the lock-stitch type, the combination of a stationary block having a shallow cylindrical recess in the front face thereof, a rock-shaft mounted at the rear of said block and projecting through the same into said recess, means for oscillating said shaft, an arm projecting laterally from said shaft, an arcuate thread-hook carried by said arm and adapted to oscillate around the margin of said recess, 60 said thread-hook having a forwardly-directed point and a recurved nose, a bobbin-case loosely mounted in the center of said recess, 65

and a bobbin-bracket adjustably secured to said block and adapted to hold said bobbin-case loosely in position.

45. In a shoe and leather sewing machine of the lock-stitch type, the combination of a stationary block having a shallow cylindrical recess in the front face thereof, a rock-shaft mounted at the rear of said block and projecting through the same into said recess, means for oscillating said shaft, an arm projecting laterally from said shaft, an arcuate thread-hook carried by said arm and adapted to oscillate around the margin of said recess, 70 said thread-hook having a forwardly-directed point and a recurved nose, a bobbin-case loosely mounted in the center of said recess, a bobbin-bracket adjustably secured to said block and adapted to hold said bobbin-case 75 loosely in position, said bobbin-bracket having a central aperture, a bobbin adapted to be rotatably mounted within said bobbin-case and to be withdrawn through the open face of the case and through said aperture, 80 and a back plate secured to the back of the recess and adapted to shield the bobbin-case and thread-loop from the oscillating parts.

46. In a sewing-machine of the lock-stitch type, the combination of a cam carried by the main shaft of the machine, a cam-lever reciprocated by said cam, a stationary thread-hook block, a gear-segment pivotally mounted to the rear face of said block, an intermediate link, universal joints connecting said intermediate link with said cam-lever and said gear-segment, an oscillating thread-hook shaft mounted transversely in said block, a pinion carried by said shaft and meshing with said gear-segment, a thread-hook arm extending radially from the front end of said shaft and into a recess in the front face of said block, and an arcuate thread-hook secured to the end of said arm and adapted to oscillate around said recess. 95

47. In a sewing-machine of the lock-stitch type, the combination of a cam carried by the main shaft of the machine, a cam-lever reciprocated by said cam, a stationary thread-hook block, a gear-segment pivotally mounted to the rear face of said block, an intermediate link, universal joints connecting said intermediate link with said cam-lever and said gear-segment, an oscillating thread-hook shaft mounted transversely in said block, a pinion carried by said shaft and meshing with said gear-segment, a thread-hook arm extending radially from the front end of said shaft and into a recess in the front face of said block, 105

an arcuate thread-hook secured to the end of said arm and adapted to oscillate around said recess, a bobbin-case loosely mounted in the center of said recess and having a thread-aperture and a depending lip at its lower side, a post centrally mounted in said bobbin-case, 115 a bobbin-bracket adjustably secured to said thread-hook block and loosely retaining said bobbin-case in place and having a recess in the edge thereof receiving said lip on the 120

bobbin-case, a bobbin rotatably mounted on the central post of said case, and a retarding device adapted to retard the rotation of said bobbin.

5 48. In a sewing-machine of the lock-stitch type, the combination of a cam carried by the main shaft of the machine, a cam-lever reciprocated by said cam, a stationary thread-hook block, a gear-segment pivotally mounted to the rear face of said block, an intermediate link, universal joints connecting said intermediate link with said cam-lever and said gear-segment, an oscillating thread-hook shaft mounted transversely in said block, a pinion carried by said shaft and meshing with said gear-segment, a thread-hook arm extending radially from the front end of said shaft and into a recess in the front face of said block, an arcuate thread-hook secured to the end of said arm and adapted to oscillate around said recess, a bobbin-case loosely mounted in the center of said recess and having a thread-aperture and a depending lip at its lower side, a bobbin-bracket adjustably secured to said thread-hook block and loosely retaining said bracket in place and having a recess in the edge thereof receiving said lip on the bobbin-case, a post centrally mounted in said case, a bobbin rotatably mounted on the central post of said case, a retarding device adapted to retard the rotation of said bobbin, a spreading-finger projecting downwardly and centrally into the incipient thread-hook, and means for oscillating said spreading-finger.

35 49. In a shoe and leather sewing machine of the lock-stitch type, an arcuate thread-hook having a forwardly-directed point adapted to enter the thread-loop, a recurved nose adapted to hook over and draw out the thread-loop, a tapered groove on the inner face of said hook between said point and nose adapted to receive the barbed point of the needle and to deliver the thread-loop therefrom, a waist portion adapted to be secured to a rock-arm, and a tail-shield comprising a radial flange and an axial flange, said axial flange being obliquely pointed, whereby to push out the thread-loop away from the needle and prevent it from engaging therewith, substantially as described.

50 50. In a shoe and leather sewing machine of the lock-stitch type, an arcuate thread-hook having a forwardly-directed point adapted to enter the thread-loop, a recurved nose adapted to hook over and draw out the thread-loop,

a tapered groove on the inner face of said hook between said point and nose adapted to receive the barbed point of the needle and to deliver the thread-loop therefrom, a waist portion adapted to be secured to a rock-arm, and a tail-shield comprising a radial flange and an axial flange, said axial flange being obliquely pointed, whereby to push out the thread-loop away from the needle and prevent it from engaging therewith, in combination with a bobbin-case loosely sustained in the center of the raceway of said thread-hook, a bobbin-bracket adapted to loosely retain said bobbin-case in place, and means loosely engaging said bobbin-case with the bracket, whereby to keep the same from rotation while permitting the thread-loop to be drawn around said bobbin-case.

5 51. In a shoe and leather sewing machine of the lock-stitch type, the combination of a stationary block-carrying stitching mechanism, a bobbin-case loosely retained in the center of said block, a bobbin-bracket adapted to loosely retain said bobbin-case in position, means for securing said bobbin-bracket to said block comprising a pair of projecting studs and nuts secured thereover, and means for adjusting said bobbin-bracket to adjust the play of the bobbin-case comprising an adjustable nut mounted on one of said studs behind said bobbin-bracket.

5 52. In a lock-stitch shoe and leather sewing machine, the combination of a stationary thread-hook block having a shallow cylindrical recess formed in its front face, a rock-shaft transversely mounted in said block and extending into said recess, a disk formed on the front end of said rock-shaft, a radial arm extending from said disk, an arcuate thread-hook secured on the end of said arm and adapted to oscillate around the marginal portion of said recess, a central boss rising from said disk, a back plate secured to said block and covering said disk and having a central aperture therein adapted to receive said boss, a bobbin-case loosely mounted in the center of said recess, and a bobbin-bracket adjustably secured to the face of said block and extending over the marginal portions of said bobbin-case to hold the same loosely in place.

In witness whereof I have hereunto set my hand in the presence of two witnesses.

JOSEPH LOUIS KIEFFER.
